LEONARD B. HARRIS, OF HADDON HEIGHTS, NEW JERSEY, ASSIGNOR TO HARRIS PATENTS COMPANY, OF NEW YORK, N. Y., A CORPORATION OF DELAWARE.

INTERNAL-COMBUSTION ENGINE.

1,192,520.

Specification of Letters Patent. Patented July 25, 1916.

Application filed October 30, 1914. Serial No. 869,392.

To all whom it may concern:

Be it known that I, LEONARD B. HARRIS, a subject of the King of Great Britain, residing at Haddon Heights, in the county of 5 Camden and State of New Jersey, have invented new and useful Improvements in Internal-Combustion Engines, of which the following is a specification.

This invention relates to an internal combustion engine and while the invention relates particularly to an engine of the Diesel type, such as that set forth in my application Serial No. 726,045, filed Oct. 16, 1912, many features of the invention are applicable to engines of other types.

In one aspect, certain features of the invention may be regarded as improvements upon the invention disclosed in my application referred to above. In the invention 20 covered by that application, the engine embodies in its construction scavenging air cylinders operated in conjunction with power cylinders so that the mechanism of the engine renders the engine capable of 25 starting by means of compressed air admitted to the air cylinder. The operating lever which started the engine on air also admitted fuel to the power cylinders so that after the engine was started on air, its 30 operation continued automatically on fuel. The arrangement was such that the air was cut off from the air cylinders as soon as the fuel was turned into the power cylinders. In other words, when the engine had been 35 started on air, the driving of the engine with fuel began as soon as the driving by compressed air had ceased.

One of the objects of the present invention is to provide an engine of this class with a 40 construction which will operate in such a way that the driving of the engine by means of compressed air may be continued after the power cylinders are operating with the fuel, the general purpose being to enable the 45 engine to gather speed and power quickly.

A further object of the invention is to provide an arrangement whereby the control of the operation of the air cylinders, when desired, may be rendered independent 50 of the operation of the power cylinders, the general purpose being to enable the engine when desired, to be driven as an air motor by means of compressed air alone.

A further object of the invention is to provide improved means for controlling the re-

lation of the air cylinders and the power cylinders, including improved valve means operating with small clearance losses and enabling the air cylinders to operate as scavenging cylinders for the power cylinders.

Further objects of the invention will appear more fully hereinafter.

The invention consists in the general combination of parts and simplicity of details 65 hereinafter described, all of which contribute to produce an efficient internal combustion engine.

The preferred embodiment of my invention will be particularly described in the 70 following specification while the broad scope of my invention will be pointed out in the appended claims.

The invention also consists in the method described hereinafter.

In the drawings: Figure 1 is a perspective partly broken away and illustrating an engine embodying my invention. Fig. 2 is a vertical section taken through the cylinders of the engine and further illustrating 80 the preferred arrangement of the parts.

Fig. 3 is a front elevation of a control device which constitutes a feature of the invention, certain parts being broken away. Fig. 4 is a vertical section through the control device taken about on the line 4-4 of Fig. 3. Fig. 4^a is a vertical cross section through the valve chest shown in Fig. 4, taken about on the line 4^a-4^a of Fig. 4. Fig. 5 is a front elevation and partial section further illustrating the preferred arrangement of the control device illustrated in Fig. 3. Fig. 6 is a front elevation showing parts of the control device at a critical point in the movement thereof. Fig. 6^a is 90 a view similar to Fig. 6 but representing parts arranged so that the air control can be operated independently of the fuel control. Fig. 7 is a view showing certain parts in section taken on the line 7-7 of Fig. 6. 100

Fig. 8 is a detail partially in section illustrating a lost motion device for preventing the feeding of fuel to the power cylinders until the engine has been started on compressed air. Fig. 9 is a vertical section taken 105 through the valve which controls the communication between the cylinders and between the cylinders and the air manifold, which holds the air for scavenging the power cylinders. Fig. 10 is a front eleva- 110

tion and partial section showing the valve illustrated in Fig. 9 and its contiguous parts. Fig. 11 is a vertical section showing a valve of rotary type which I may use to perform the function of the valve illustrated in Figs. 9 and 10. Fig. 12 is a vertical section taken near the plane of the section Fig. 11 and further illustrating the valve. Fig. 13 is an elevation partially in section and broken away, further illustrating the valve arrangement when the valve is of the rotary type. Fig. 14 is a view showing the figure which will appear upon an indicator card if taken from the scavenging cylinder when starting the engine on compressed air. Fig. 15 is the card of the air cylinder produced during the first revolution. Fig. 16 is the card produced on the second revolution, and each succeeding revolution while running on compressed air. Fig. 17 is the card which is produced by the scavenging cylinder operating simply as a scavenging cylinder. Fig. 18 is a compression card taken from the power cylinder while the engine is being started by air and before oil is admitted into the power cylinder.

The pressures shown on the cards are only approximate.

Before proceeding to a detail description of the invention, it will facilitate the disclosure of the invention to state that in the embodiment of the invention described, the cylinder arrangement involves the use of air cylinders preferably arranged in tandem with the power cylinders, and the arrangement for starting the engine is extremely simple. A hand operated member is provided, the first movement of which operates to admit compressed air to the air cylinders to start the engine with compressed air. If the movement of the hand operated part, such as a hand wheel, is further continued in the same direction, fuel will be admitted to the power cylinder or cylinders and the engine will be driven by means of fuel and compressed air. If the movement of the hand operated member is continued still further, the driving of the engine on compressed air will be discontinued automatically and the engine will then run regularly on fuel as its motive power.

The engine may comprise as many cylinders as desired. In the accompanying drawing, I have illustrated in detail only one power cylinder and its corresponding scavenging cylinder, this being sufficient to illustrate the preferred construction of the engine as to the cylinders.

Referring more particularly to the parts, 60 represents the engine frame or base, which may be of any suitable form carrying a crank shaft 21 to which the connecting rods 22 of the engine attach. The connecting rods 22 attach to wrist pins 23 each of 65 which is carried upon a trunk piston 24

which forms the piston for the air cylinder 25. Said trunk piston 24 has a tubular extension 26 which forms the piston for the power cylinder 27. The power cylinders are provided with exhaust ports 28 which communicate with the exhaust manifold 29 which may have a water jacket 30. The engine is provided with an air manifold 31 which communicates through a passage 32 and ports 33 with the cylinder 27 for the admission of scavenging air which passes across the upper face of the piston 26 and carries the gases of combustion out through the ports 28. The air cylinders 25 have air ports 34 the communication of which with the ports 32 and the air manifold 31 is controlled by valve means 35 which includes the intercepting valve 39. This intercepting valve is preferably fluid controlled that is, automatically by the admission of a fluid such as air. The preferred construction of the intercepting valve is illustrated in Figs. 9 and 10; each intercepting valve preferably comprises a housing 36 in which there is rigidly mounted tubular bushings 37^a and 37^b, the bushing or cage 37^b being formed with a seat 38 for a movable piston valve 39 which is adapted to move up or down in the bushings. The bushing or cage 37^b is provided with ports 40 communicating with a chest 41, which chest communicates with the port 34. The lower portion of the valve 39 has a reduced neck 42 whereby an annular circumferential passage 43 is formed.

I prefer to provide mechanical driving mechanism driven by a moving part of the engine for actuating the admission valves periodically at the proper times to admit air to the intercepting valve 39 and through the coöperation of which this air is admitted to the air cylinders or scavenging cylinders in driving the engine on compressed air, as later clearly described. When the engine is at rest or running on fuel, however, the admission valves are not in coöperative relation with the mechanical driving mechanism. I prefer to bring the valves and the mechanical driving mechanism into coöperative relation by fluid operated means preferably pneumatic means. I accomplish this in a very simple manner by means of the air pipes or conduits 46 and 50.

When the engine is to be reversible, I provide two admission and cut-off valves 44 for admitting and cutting off air to the intercepting valves. These valves are preferably fluid controlled and are preferably located one on each side of the intercepting valve; and are duplicates of each other in construction; there are two such valves, one corresponding to each direction for the engine, because they are to be operated at different times in relation to the piston position to drive the engine ahead or astern, that is, in a reverse direction.

I shall now describe one of the valves 44 and its contiguous parts of the preferred construction and arrangement shown in Fig. 10. The valve 44 corresponding to a certain direction of drive for the engine, when the engine is at rest is on its seat 54 closing the inlet 54^a, but when the air is turned on in pipe 46, this valve is blown across the air chest 54^b against the seat 45. The seat 45 is preferably formed in the lower end of a bushing 47 which has a tubular head forming the outlet from the air chest with ports 48 communicating with a passage 49 which communicates with the aforesaid annular passage 43. It is understood that when the engine is to be driven by compressed air in one direction, compressed air is admitted in the pipe 46 for example, but not in the pipe 50, and vice versa. When the valve 44 is raised to its seat 45 by the admission of the air, a roller 51 carried by the upper end of the stem 52 is in a position to be engaged by a mechanically operated member such as cam 53 on the cam shaft 35', said cam shaft 25 extending longitudinally of the engine and being driven through a substantially vertical shaft 55 and gearing 55^a from the main shaft 21 of the engine in some such manner as that illustrated in Fig. 1. When air is not turned on in the pipe 46, the valve 44 rests upon its lower seat 54. It is understood also that the intercepting valve 39 is normally in its extreme low position in which it is illustrated in Fig. 2.

The space between the bushings 37^a and 37^b forms an annular port 56 with which the port 49 communicates. On the front side this port 56 communicates with a pipe 57 which conducts the air down into a small air cylinder 58 or pilot cylinder in which moves a piston 59 having a stem 60 connected with the valve 39; the upper valve bushing 37^b is provided with a cross bar or bridge 61 against which seats a spring 62 the lower end of which seats over a boss 63 at the lower end of the valve 39 and this spring is compressed by the upward movement which is imparted to the valve by the compressed air in the pilot cylinder 58. When the valve 39 is forced upwardly so that its upper end 64 comes against the seat 38, communication is cut off between the port 34 and the manifold 31; but through the annular port 43 communication is maintained with the air pipe 57 so that the air pressure in the pilot cylinder 58 is maintained and the valve held on its upper seat.

In the bridge 61 there is mounted a stem 65 which extends upwardly and which carries a guard 66; under this guard 66 there is mounted a spring 67 the lower end of which thrusts against a disk valve 68 which normally closes the upper end of the valve bushing 37^b. In order to cushion the upward movement of the piston 59, the upper end of the cylinder 58 is provided with a stop-cock 69. When the stop-cock is open, the air is driven out and by partially closing the stop-cock, the exit of the air is choked and a cushioning effect results. A similar cushioning effect is brought about when the valve 39 is forced back by spring 62 to its lowest position. For this purpose, I prefer to provide the lower bushing 37^a with a bleeder screw 70 having a cut in its side which opens the lower end of the case to the atmosphere. By adjusting the screw 70 of course, the amount of opening can be regulated to control the cushioning effect. An air space 71 is formed over each valve 68 and these air spaces 71 are in communication with the air manifold 31 and the scavenging ports 32.

The engine as stated, is preferably of the Diesel type, each of the heads 72^a of the power cylinders 27 being provided with fuel admission means preferably in the form of an atomizer 72 which opens mechanically at the proper times through the operation of mechanism 73 disclosed in detail in my former application Ser. No. 726,045. This mechanism 73 is preferably operated partly from the aforesaid cam shaft 35' and partly from the control device 121 to be disclosed hereinafter and which controls the admission of air to the pipes 46 and 50. This mechanism 73 preferably comprises rockers or actuators for the valves or atomizers 72 which are periodically rocked by cams 75 on the aforesaid cam shaft 35'. Each atomizer 72 has a stem 75 which rides upon two levers 77 fulcrumed at 78, the outer ends of the levers being connected with actuated stems 79. These levers are arranged so that neither lever prevents the opening of the atomizer by the other. This atomizer is set forth clearly in my application Serial No. 769,925. The lower ends of these stems are provided with rollers 80 resting on the upper surface of the corresponding rockers 74. The rockers 74 rock about the pivot pins 81 and are held by springs 82 on their cams 75. The actuating stems 79 slide freely through swiveled guides 83, each of said guides having a swivel connection with a crank arm 84; and each of these crank arms 84 is rigid with the adjacent arm 85 connected by the link 86 with a slide 87. These slides are pulled down by the bell cranks 89 and pulled up by the springs 87^a and guided by guides 87^b (Fig. 2). The position of these slides 87 determines the positions of the crank arms 84 and also the point where the rollers 80 will lie on the rockers 74; this evidently determines the amount of movement of the levers 77 and the atomizer stems 76. The levers 77 are pulled down by any suitable means such as the springs 88 attached to them. The slides 87 are controlled by a T-arm 89 having its pivot at 90 and there

is one of these T-arms 89 corresponding to each power cylinder; and the different T-arms 89 are connected together by a link 91 which in turn is controlled by my control device 121 about to be described. The atomizer stems 76 are held closed and down on their levers 77 by springs 76^a. The lower end of each stem has a conical point forming a valve for the atomizer. When the 10 stem is raised, a charge of fuel and air pass into the power cylinder through openings 76^b. In other words, each atomizer is valved, or valve controlled. In connection with the pumping mechanism, I prefer to provide 15 variable means for varying the amount of fuel delivered by the pumps.

The fuel for the power cylinders is supplied to them individually through pipes 92^a and 92^b from pumping mechanism 92, a 20 preferred form of which is disclosed in detail in my co-pending application Serial No. 768,484, filed May 19, 1913. This pumping mechanism 92 preferably comprises a number of pumps 93 the plungers 94 of which 25 are each connected by an oscillating block and sliding connection 95 with the arm 96 of a rocker 97 having its fulcrum at 98. Each rocker 97 has an arm 99 and these arms are disposed on opposite sides of a cam or eccentric, 100, said cam or eccentric being 30 fixed on a cam shaft 101 which is driven from the vertical shaft 55 by suitable gearing 102. A variable adjustment is provided 35 for the fulcrum pins 98 enabling them to be controlled by the governor 109 of the engine and also by my control device. For this purpose, the fulcrum pins 98 of the rockers 97 are carried on slides 103 mounted to slide horizontally, and on each pin 98 there is 40 loosely attached a double worm sector 104; the upper teeth of these sectors engage worms 105 on the same shaft 106, said worms having right and left hand threads so that for a certain direction of rotation of 45 the shaft 106 the fulcrum pins 98 will be adjusted toward each other or away from each other. The lower teeth of the double sectors 104 mesh with similar worms 107 carried on a shaft 108. By rotating the shaft 50 108, the sectors may be rotated so as to adjust the pins 98 toward or away from each other. When one pair of worms is adjusting the sectors, the teeth at the opposite end of the sectors roll on the other worms as though 55 they were racks. The worm shaft 106 is controlled by the governor 109 of the engine by means of a lever 10 which lever is connected by a link 111 with a rack 112 meshing with a pinion 113 on the shaft 106.

60 Compressed air is brought from a reservoir to the atomizer of each cylinder by a pipe such as pipe 76^a; and the compressed air reservoir (not illustrated) is supplied with compressed air by a compressor 76^b 65 driven in any suitable manner from shaft 21.

A pipe 76^c leads from the air compressor to the air reservoir. The governor 109 may be of any suitable construction. The fuel for the pumps may be supplied from a suitable reservoir 114 having a pipe 115 connecting 70 with the inlet pipes 116 for the pumps. The cam 100, as it turns around, will strike first one of the arms 99 and then the other, and in this way operate the pump plungers alternately; any number of cams or eccentrics 75 100 can be attached on the shaft 101 corresponding to the number of levers 99 and pumps 93 and power cylinders 27. There is also a pair of pumps to correspond with every pair of cylinders. The amount of 80 stroke of the pumps will depend upon the position of the fulcrum pins 98 which will evidently give a range from zero or no stroke to the maximum possible stroke.

Under the influence of the governor, the 85 fulcrum pins 98 may be moved so far apart that the pumps will have no stroke, and this will cut off the fuel supply. The worm shaft 108 is controlled from my control apparatus by means of a pinion 117 on the 90 shaft 108 which meshes with the rack 118 connected with my control apparatus. This rack simply lies on the pinion, and the outer end of the rack has a handle 119 which enables the rack to be raised when desired to 95 disconnect it from the pinion. At this time, the shaft may be rotated directly by means of its attached hand wheel 120. This enables the several positions of the worms 107 to be altered when desired.

I shall now proceed to describe my control device and its relation to the other mechanism and particularly its relation to the intercepting valve. With my control device 121, there is preferably an air chest 100 or valve box 122 the preferred construction of which was disclosed in my former application Serial No. 726,045. As illustrated in Figs. 4 and 4^a, this air chest is supplied from a suitable source with air under pressure by 105 a supply pipe 123 which may let the air into either of two ports 125 from which it is normally closed off by two throttle valves 124, pressed toward their seats by springs 124^a and the pressure in the air chest 122. 110 If one of these valves 124 is opened, communication is established from the interior of the chest 122 and its corresponding port 125 which connects with the aforesaid pipe 46. When the other valve 124 is open, the air 115 is let in to the pipe 50. In order to raise either of these valves 124, as may be desired, each valve has a downwardly extending stem 126 and these stems have outwardly projecting dogs 127 which pass through 125 slots 127^a and rest upon toes 128 of a rocker 129. The spindle of this rocker carries a rigid arm 130 and this arm has a pin and slot connection 131 with the lower end of a rack 132, said rack having teeth in mesh 130

with the segment 133. This segment may be rotated by an air controlling member preferably in the form of a lever 134. I provide an arrangement for enabling this lever 134 to be moved independently of the hand wheel 148'. For this purpose, the spindle 135 of this segment preferably has a flat extension which is received in a slot 136 formed in the lever 124, said flat extension being held normally at the upper end of the slot by a removable pin 137. The case of the air chest 122 is provided with a quadrant 138 which is provided at any suitable point with means such as the notch 139 for indicating the neutral point of the lever. The lever 134 has a spring pressed pin 140 which engages the notch when the lever is in its vertical or neutral position. In order to move this lever 134 to admit air automatically to the air cylinders to start the engine when the controlling member or wheel is moved, I prefer to provide an actuator 141 which is preferably in the form of a slide mounted to slide horizontally in the guide 142. This actuator is preferably formed with a central slot in the opposite ends of which engaging means such as dogs 143 are mounted to move on pivot pins 144, said dogs being spring pressed, for which purpose they are preferably connected by a spring 145 which tends to force them inwardly through the slot. The dogs are preferably provided with laterally projecting lips 146 on their upper sides which engage the upper edge of the slots and limit the inward movement of the dogs.

When the lever 134 is in its neutral or normal position and the actuator 141 is in its normal or neutral position, the lever lies between the dogs 143 so that if the actuator 141 is moved toward the right, the left hand dog engages the lever and moves it toward the right, and vice versa. Movement in one direction will open one of the valves 124 and movement in the other direction will open the other valve 124. The upper sides of the dogs near the plane of engagement with the lever 134 are formed with curved faces 147, (see Fig. 6). These faces are cut away in this manner so that after the actuator comes to a predetermined point, the lever will be released from the dog which has been moving it. The lever will then return to its normal or neutral position through the action of a spring 148 which is attached to the end of the lever, the lower end of the spring being anchored at 149, Fig. 4.

In order to move the actuator and at the same time control the admission of fuel and regulation of the pumps, to control the action of the power cylinders, I prefer to provide a hand operated member such as a hand wheel 148', said hand wheel being attached to a spindle 148^a carrying a worm

149', said worm meshing with the worm wheel 150. This worm wheel has a pin and slot connection with the actuator, for which purpose it carries on its inner face a block 151 pivoted on a pin 151^a, and this block slides freely in a vertical slot 152 which is formed between two horns 153 which extend down from the actuator. From an inspection of Fig. 5, it will be evident that if this worm wheel 150 is rotated toward the right, its spindle 154 will rotate toward the right, the block 151 will also swing toward the right, so as to displace the actuator 141 toward the right, and at the same time, the block will move slightly downwardly in the slot 152. The spindle 154 has an arm 155 which extends downwardly from it and to this arm attaches the link 91 which controls the T-arms 89 which in turn control the operation of the atomizer stems 76. This arm 155 is not rigidly attached to the spindle 154, but is preferably attached to the spindle through the medium of a lost motion device preferably comprising a bushing 156 rigid with the arm having a circumferential slot 157 in which moves a key 158 carried by the spindle; from an inspection of Fig. 8, it will be evident that if the spindle is rotated in either direction, it will not affect the arm in any way, until the key 158 engages the bushing. This arrangement allows a sufficient movement of the spindle to run the engine on air, and on air and oil before the air is cut off. The inner end of the spindle 154 is rotatably mounted in the bracket 159 and beyond this bracket an upwardly extending arm 160 is attached, which arm is connected with the link 161 which extends downwardly, and the lower end of this link is attached to an arm 162 of a bell crank lever 163, the opposite arm 164 thereof has an adjusting pin and slot connection 165 with the aforesaid link 118 the outer end of which is formed with rack teeth 167 which engage with the aforesaid pinion 117.

A bushing similar to the bushing 156, which is illustrated in Fig. 8, is fitted into the hub of arm 160 and is attached rigidly to arm 160 so that a similar lost motion occurs in starting the pumps also. Attention is called to the fact that when the parts are in their neutral position, the link 160 is on its upper dead center so that whatever be the direction of rotation of the hand wheel 148' to start the engine, the same direction of movement will be given to the bell crank lever 163, that is, in either direction of driving the engine, the arm 162 will be depressed.

In order to indicate what is taking place in the control of the engine corresponding to any given position of the wheel 148', I prefer to provide a dial 168 coöperating with which there is provided a pointer 169

which is in a vertical position in the neutral or "stop" position of the mechanism. If the hand wheel 148' is rotated in the direction to move the pointer 169 toward the right, there will be an admission of air only to the engine until the pointer arrives at the line 170 of the dial; beyond this point and until the pointer reaches the line 171, the engine will be driven on compressed air in the scavenging cylinders, and oil in the power cylinders, and beyond the line 171 the engine will be driven on fuel only. All of which is indicated by the dial. In using the term oil, it is understood, of course, that I do not wish to be limited to oil fuel, but simply use this term to indicate a fuel.

Though it is not necessary to start the engine, I prefer to provide a hand operated cam 172 which is disposed between the arms 99 of the pump as indicated in Fig. 1, and this cam can be rotated or oscillated by means of a suitable crank 173 to operate the pumps by hand.

Arrangement is made for disconnecting the lever 134, Fig. 6^a, from the actuator in order to enable the engine to be run continuously by air alone, and without moving the hand wheel 148' by means of which the engine is ordinarily started. For this purpose, the aforesaid slot 136 is provided. By referring to Fig. 6, it will be seen that by removing the pin 137 the lever 134 can be pulled up, extending the spring 148; the pin 137 is first removed and then replaced in the lever above the spindle, as shown in Fig. 6^a. When the lever is in this position, its lower end is lifted high enough to clear the dogs 143 so that the lever can be operated freely and independently of the actuator 141.

It is evident that the wheel 148' constitutes means for controlling the admission of fuel charges to the power cylinders, and through the medium of the lever 134 this wheel may also control the admission of air to the scavenging cylinders. It is also evident that if desired the lever 134 can be pulled up as indicated in Fig. 6^a and be operated by hand independently of the hand wheel 148'. In other words, this lever 134 which controls the admission of compressed air is operable by and also independently of the hand wheel 148'.

One of the functions of the actuator 141, after the lever 134 has released itself, as illustrated in Fig. 6, is to prevent an accidental operation of the lever which would cause a flow of air in the engine to oppose the running direction, and for this purpose each end of the actuator is provided with a projection or buffer 174, and the actuator is arranged so that just at the time that it releases the lever 134, one of these buffers 174 is substantially under the notch 139, so that when the lever 134 swings back to its neutral position it does not oscillate there, but

strikes and comes to rest against the buffer; furthermore, it will be evident that as long as the actuator is in this position it will be impossible to move the handle of the lever toward the right, that is in a direction which would admit air to oppose the driving direction of the engine occurring at that time. But, it is still possible to move the lever 134 to the left, admitting air in the direction that the engine would then be running; this may be done if desired to augment the power of the power cylinders by admitting compressed air to the scavenging cylinders at the same time.

In order to indicate to the operator whether the engine will go ahead or astern for a certain direction of rotation of the wheel 148', I prefer to provide the spindle 148^a of the hand wheel 148' with a screw 176 and on this screw runs a nut in the form of a saddle 177, the upper end of said nut running in a slot 178 in the casing 179 of the control device and having a pointer 180. On one side of the neutral position of this pointer is indicated the word "Ahead" and on the other side the word "Astern."

Instead of employing a valve of the type illustrated in Figs. 9 and 10, I may employ a valve of rotary type such as that illustrated in Figs. 11 to 13, and when using this type of valve, I prefer to place both the inlet valves on the same side of the intercepting valve. These valves are very efficient in operation on account of their small clearance spaces. The preferred form of this type of valve comprises a valve casing 181 in the upper portion of which one or more valves 182 are provided, through which air is admitted to the manifold 183. Immediately under these valves 182, I provide a rotary valve 184 having a port 185. When the valve is in the open position, this port 185 opens communication from passage 186 from the air cylinder so that air can pass into the air space 187 over the rotary valve and up through the valves 182. The air space 188 over the valve 182 connects the manifold 183 with the scavenging port 189 to which air is admitted to each power cylinder. At the right of the casing 181, as illustrated, two inlet or cut off valves 190 are provided which are similar in construction to the inlet valve 44 already described, said valves having stems 191 which extend upwardly and carry rollers which may engage either of two cams 192 on a cam shaft 193. Suppose the air is turned on in the pipe 194, instead of the pipe 195; this will raise the corresponding valve 190 onto its upper seat 196 and put the upper end of the same into position to be engaged by its corresponding cam 192. When the cam depresses the valve, air passes through a port 197 into the lower end of a pilot cylinder 198 and forces upwardly a piston 199 mount-

ed in this pilot cylinder. A stem 200 extends downwardly from the piston and has a pin and slot connection with the arm 201 attached rigidly to the spindle of the valve 184 so that when the piston 199 has completed its upward movement the valve 184 will be rotated so that the port 185 will occupy the position indicated by the dotted lines, Fig. 12. Furthermore, the piston 199 will now move upwardly sufficiently to open the passage 197 so that it will communicate with the port 202 and this port connects with a pipe 203 which carries the air down to the port 204 leading into the valve 184. In the new position of the valve, the port 185 opens communication then from the port 204 to the port 186 which admits air into the air cylinder and at the same time intercepts the passage of air into the chamber 187. The piston 199 is preferably mounted in a suitable liner 205 and is pressed downwardly toward its normally low position by means of a spring 206; Fig. 11 illustrates the piston in its lowest position. In order to regulate the cushioning effect on the piston 199 the cylinder liner 205 is provided with a bleeder passage 205^a similar to that shown at 70 in Fig. 10. In the details of their construction, the valves 190 are similar to the valve 44 already described, and they operate in substantially the same way, that is, when the air is turned off in either pipe, the corresponding valve 190 rests on its lower seat 207. It is understood that the admission of air in one of the pipes moves its corresponding valve to its upper seat, while the air which passes into the air space 208 between the valve seats holds the corresponding inactive valve on its lower seat. The cams 192 are arranged in relative position to the cranks of the engine so that one will admit air at the correct time to turn the engine over "ahead" and the other, in such a position that it will admit air at the right moment to turn the engine over "astern." A suitable water circulating system is provided including a connection 30^a between the water jacket 30 of the exhaust and the water chamber 72^b of the head; and a pipe 30^b connects with a water jacket 30^c of the cylinder 27.

Suppose that it is desired to start the engine in the regular way; turning the hand wheel 148' will rotate the worm 149' and impart corresponding rotation to the worm wheel 150. This will move the block 151 which slides in the slot 152 and this will cause a sliding movement of the slide or actuator 141. Suppose that this movement is in a right hand direction so as to displace the actuator toward the right, as indicated in Fig. 6; as this movement takes place, the lower end of the lever 134 is engaged by the left hand dog 143 and the lever is moved toward the right. This first movement of the hand wheel, while it rotates the worm

wheel 150 and the spindle 154 of the worm wheel, it will not impart any movement to the link 91 which controls the opening of the atomizers. This mode of operation occurs on account of the lost motion device 70 illustrated in Fig. 8. The movement of the lever 134 however, operates to rotate the segment 133 and this depresses the lever 130 and rocks the toe cam 129 so that the right hand stem 126 of the right hand valve 124, 75 as viewed in Fig. 4, is raised. This admits compressed air to the pipe 46. When the air is admitted to the pipe 46, it raises the valve 44, as illustrated in Fig. 10, off its seat 54 and shoves it against its upper seat 45. This 80 prevents any further passage of the air toward the cylinder; however, if it should happen that the cam 53 is in a position to prevent the valve 44 closing against its upper seat, air would be at once admitted 85 past the valve 44. This will start the engine, and thereafter the cam 53 will depress the valve 44 periodically and at the proper moments to keep the engine running.

It is understood that before the air is admitted the intercepting valve 39 is down in its lowest position, as indicated in Fig. 2. When the air passes the valve 44, it goes through port 49 and into the annular port 56, through pipe 57 into the lower end of 90 the pilot cylinder 58, and acts on the piston 59 and forces the intercepting valve 39 to its uppermost position. This brings the upper end of the intercepting valve against the seat 64 and cuts off communication from 95 the port 34 into the port 32, Fig. 2, and the space 71 and manifold 31. Furthermore, the moving of the valve 39 to its uppermost position brings the annular port 43 into a position to open communication from the 100 annular port 56 to the passage 34 and this admits starting air into the air cylinder 25, Fig. 2. This drives the piston 24 downwardly and starts the engine. After piston 24 has moved down to about two thirds of its 105 stroke, the cam 53 lets the stem 52 of the valve 44 move up and the air flowing against the valve from the pipe 46 immediately closes the further passage of air into the ports 49, 56 and pipe 57 and cylinder 58. 110 This corresponds to the point of cut off for admitting air to the air cylinder, and after this the air in the cylinder expands and the expansion continues until the exhaust from the cylinder occurs through the ports 120 25^a, Fig. 2; however, until the exhaust occurs, the air pressure in the cylinder 25 acting back through port 34, passages 43, 56, pipe 57, cylinder 58, under piston 59 is sufficient to maintain the valve 39 in its uppermost or closed position. After the piston 24 passes the port 25^a, the air flows out through the air conduit 25^b and through the exhaust silencing perforations 25^c to the atmosphere. This reduces the pressure in the 130

cylinder 25, port 34, passages 43, 56, pipe 57, cylinder 58 to substantially atmospheric pressure thereby allowing the spring 62 to force down the intercepting valve 39 to its lowest or normal position, see Fig. 2, and restoring communication between ports 34 and chamber 71 and manifold 31, before compression begins on the scavenging stroke. On the upstroke of the piston, the air which remains in the cylinder is slightly compressed above the port 25^a and when this pressure is raised sufficiently, it will lift the valve 68 and air will flow into the space 71 and into the air manifold 31. This will maintain the proper air pressure in the manifold 31 which holds the scavenging air for the adjacent power cylinder 27. In this way, the engine is started on air alone and it will continue to run on air alone until the pointer 169 reaches the line 170, which corresponds to the amount of lost movement at the slot 157, as illustrated in Fig. 8, and when the pointer reaches this line 170, the link 91 receives a movement in the proper direction. This will move the corresponding arm 84 outwardly over its corresponding rocker lever 74 and the corresponding atomizer lever 77 will begin to operate. The engine then operates on fuel and compressed air. At each up-stroke of the air piston 24 a cylinder full of scavenging air will be compressed and forced at low pressure into the air manifold 31. On each down-stroke the air cylinder and the intercepting valve operate as described above, until air starting air is cut off. When the upper face of the power piston 26 passes the ports 32 and 28, scavenging air blows across the upper face of the power piston and carries the exhaust gases out to the exhaust manifolds 29. The scavenging air left in the power cylinder is compressed on the up-stroke. When the engine is running on fuel alone on each out-stroke free air is drawn in through ports 25^g, inlet valve 25^e, and inlet passage 25^f, to fill the cylinder 25, and on the return or inward stroke this cylinder full of free air is forced into the air manifold 31 at low pressure. Hence it is seen that the scavenging piston performs its same scavenging function whether running on fuel or being air started, and performs that function in the same way, that is in either case the cylinder full of air which is at atmospheric pressure at the commencement of the inward stroke is forced by the instroke of the piston into the manifold 31 at low pressure. This is indicated by the indicator cards to be described hereinafter. Ports 25^e allow any foul gas in the lower part of the engine to be drawn away by the engine itself.

The position of the lever 134 illustrated in Fig. 6 corresponds to the position of the pointer 169, when it is over the dial line 171.

At this point, the lever 134 is released by the dog 143 which is moving it; its spring 148 then pulls the lever 134 back to its neutral position. In coming back to its neutral position, the lower end of the lever strikes the buffer 174 at the left end of the actuator and this prevents the lever from oscillating at its neutral position. The continued movement of the hand wheel 148 in the same direction will increase the amount of opening of the atomizers and also will increase the stroke of the pump plungers 94. In this connection, it is understood that when the atomizers are put into operation the pumping mechanism 92 also is brought into operation to pump the fuel to the atomizers. Though, obviously, if desired, the pumps could be started before the atomizers began to operate. The last part of the movement of the hand wheel 148' however, will not have the effect of substantially increasing the movement of the actuator 141 toward the right for the reason that at this point of the movement the block 151 is on the extreme right and moving nearly vertically down in the lower end of the slot, and the horizontal component of its movement by the worm wheel 150 is very small. On this account, the lever 134 will not be moved by the buffer so as to turn the air on. However, if it is desired to turn the air on at any time into the air cylinder to increase the power of the engine, this can be accomplished by moving the lever 134 by hand toward the position in which it is shown in Fig. 6. It is understood that a movement of the lever in the wrong direction at this time is impossible on account of the buffer 174 being in the path of movement of the lever, which would obstruct such a backward movement. The pumps are brought into operation automatically when the pointer 169 arrives at the dial line 170, through the operation of the link 161 (see Figs. 3 and 4) and the rack 118 which rotates the pinion 117 in the proper direction. This produces a rotation of the worms 107 causing the arms 99 to approach each other and bringing them into the range of the cam 100 which is continuously driven on the shaft 101. The governor 109 also controls the position of the levers 99 by rotating the worm shaft 106 which causes a rotation of the sectors so that they approach or recede from each other according to whether more or less power is needed. The backs of the dogs 143 have inclined faces 143^a which enable the lever 134 to collapse or displace the dogs when the member 141 returns to its normal or neutral position; as the spring 145 holds the pawls yieldingly, it pulls the displaced dog back into place, (see Fig. 7).

The functions taking place in starting the engine are indicated by Figs. 14 to 18 inclusive. Fig. 14 represents the diagram which

would be produced on the indicator card in starting the engine, the card being taken from a scavenging cylinder and representing several cycles which take place in starting the engine. This diagram, for the purpose of clearness, has been separated into three distinct cards or diagrams which represent the different cycles or different phases of the performance of the engine.

- 5 10 In the card shown in Fig. 15, *a* represents the initial inlet pressure line of the compressed air in flowing into the cylinder on the out-stroke of the piston. Although this line gives the impression that the air is cut off and used simply expansively, as a matter of fact, the engine starts so rapidly that the air cannot follow the piston and maintain the admission pressure in the cylinder, hence, there is a marked loss of pressure as 15
- 15 20 the air piston moves outwardly. On the return stroke, a portion of the line lies on the atmospheric line *c*; the air is compressed slightly, as indicated by the line *b* to about seven pounds per square inch, showing that 25
- 25 30 in this stroke of the piston the cylinder is performing its scavenging function, that is, it is compressing air and forcing it into the air manifold. While this card shown in Fig. 15 is being taken, the card shown in 35
- 35 40 Fig. 18 is produced in the adjacent power cylinder, the piston of which is diametrically opposite and moving inwardly, that is, in the direction to compress the air in the power cylinder. In other words, when the 45
- 45 50 line *a* is being produced on the card, Fig. 15, line *a'* is being produced in Fig. 18, showing that the pressure gradually increases in the adjacent power cylinder. On the outward stroke of the power piston, the line *b'* is 55
- 55 60 produced so as to form a narrow crescent-shaped figure, the area of which indicates the amount of heat lost in compressing the air in the power cylinder. From the lines *a'* and *b'* it is evident that the air which is 65
- 65 70 compressed in the power cylinder gives back almost the same amount of energy which was put into it during the compressing movement.
- In the second and all consecutive out- 75
- 75 80 strokes of the scavenging piston, until starting air is shut off, the card shown in Fig. 16 will be produced, showing an admission pressure line *a''* which indicates substantially 30 pounds per square inch, and 85
- 85 90 on the return stroke, the compression line *b''* indicates the compression of the air up to about 7 pounds; and during this return stroke the cylinder performs its scavenging function, the same as indicated in Fig. 15.
- 90 95 100 As long as the engine is running on air, a card of this general character will be produced. It should be noted that in Fig. 16 line *a''* represents that very much less energy is required to turn the engine over than was 105
- 105 110 the case on the first outward stroke, as

shown at line *a* Fig. 15. The reason being that the energy is being given back in the power cylinder, as shown in Fig. 18, is assisting in the creating of the compression in the adjacent power cylinder.

70

The card shown in Fig. 17 will be produced by the scavenging cylinder when the engine is running normally on fuel alone, as a combustion engine. In this figure, the line *A*, which runs on the atmospheric line, 75 is the admission or suction line, and the line *B* is the compression line, showing that compression takes place up to 7 pounds which is the pressure in the air manifold.

It will be noticed that the line *b* Fig. 15, 80 line *b''* Fig. 16, and line *B* Fig. 17, are the same under all conditions showing that the engine performs its normal functions of compressing a charge of scavenging air whether it be air starting or running on 85 fuel.

90 In the claims where I have used the term governing, it is used in the sense of controlling. In this connection it must be remembered that many engines include in their mechanism a device known as a governor, the purpose of which is to control the speed of the engine and adapt the valves of the engine to the condition of the load on the engine. For this reason the use of the 95 word "governing" in engine practice may have a special meaning, namely, the controlling of the engine by a governor. I wish it understood, however, that in the 100 claims I have used the word "governing" in its ordinary meaning, that is, it has the same meaning as the word "controlling".

105 The cycle of operations of a Diesel multiple unit engine in which is embodied my novel method, is substantially as follows: 105 When starting the engine on compressed air, air is admitted to the scavenging cylinders alternately on the out-stroke of each piston; on the instroke of each piston, air is compressed in its power cylinder up to a 110 temperature sufficient to ignite the combustible charge which is admitted to the power cylinders in succession; on the instroke of each scavenging piston, air is discharged and held confined, and this confined 115 air is allowed to pass out through the power cylinders when their pistons arrive at a predetermined point so that they carry out the gases of combustion; the air which is left in each power cylinder is the air which 120 is compressed to furnish the oxygen and ignition temperature for the fuel charge. When the engine is operating as an air motor, the cycle is substantially the same except that the fuel is not admitted to the 125 power cylinders, that is, the admission openings are maintained closed, and the fuel pumps are out of operation. When using the engine to recharge the air starting bottles from the scavenging cylinders such as 130

may be done where an engine of this description is used as a locomotive, assuming that the atomizers are thrown out of action and the fuel pumps are put out of operation 5 in the same way that they would be in bringing the engine to rest, it would be understood then, that if the locomotive continues to run, or does what is commonly called "coasting", the momentum of the 10 train driving the engine would cause the pistons to continue their inward and outward strokes. Under these conditions, if the air starting air were admitted to the scavenging cylinders by the hand controlled 15 lever 134, in such a way that the air would endeavor to drive the engine in the opposite direction to which the momentum is driving it, the effect would be that the momentum of the locomotive would drive the scavenging 20 pistons inward against this air pressure. It being understood, of course, that the point of cut-off as controlled by the cam would become the point of admission and the usual point of admission would become 25 the point of cut-off, owing to the "reverse" cams admitting the air while the engine is being driven ahead. This would cause the starting air after acting against the scavenging piston to be forced back again into 30 the starting air reservoir with the addition of a cylinder full of free air, which would have been drawn into the scavenging cylinder before the starting air was admitted. This would have the same effect of pumping 35 up the starting air bottles, at the time having a checking effect on the momentum of the locomotive.

It is obvious that the above description sets forth a novel method of controlling and 40 operating an engine which is also of my invention.

It is understood that the embodiment of the invention described herein is only one of the many embodiments my invention may 45 take, and I do not wish to be limited in the practice of the invention, nor in my claims, to the particular embodiment set forth.

What I claim is:—

1. In an internal combustion engine, in combination, a power cylinder and piston, and a scavenging cylinder and piston therefor, arranged in tandem, means for controlling the admission of fuel charges to said power cylinder to drive the engine on fuel, 55 and means operable by or independently of said last named means for controlling admission of compressed air to said scavenging cylinder to drive the engine by compressed air alone.
2. In an internal combustion engine, in combination, a power cylinder and piston, and a scavenging cylinder and piston therefor, arranged in tandem, means for controlling the admission of fuel charges to said 60 power cylinder to drive the engine on fuel,

means operable by or independently of said last named means for controlling admission of compressed air to said scavenging cylinder to drive the engine by compressed air alone, and means for connecting said last two means to operate to drive the engine on fuel and simultaneously by compressed air admitted to said scavenging cylinder. 70

3. In an internal combustion engine, in combination, a power cylinder and piston, and a scavenging cylinder and piston therefor, arranged in tandem, fuel controlling means for controlling the admission of fuel charges to said power cylinder to drive the engine on fuel, air controlling means operable by or independently of said fuel controlling means for controlling admission of compressed air to the scavenging cylinder, said air controlling means including an operating lever, and means for connecting the same to said fuel controlling means to enable both said fuel controlling means and said air controlling means to be operated simultaneously by said fuel controlling means. 80

4. In an internal combustion engine, in combination, a power cylinder and piston and a scavenging cylinder and piston therefor, arranged in tandem, fluid operated valve means controlling the flow of air from said scavenging cylinder to said power cylinder, means for controlling the admission of fuel to said power cylinder to drive the engine on fuel, and means driven by a moving part of the engine for controlling said valve to effect air admission to said scavenging cylinder to drive the engine by compressed air alone when the fuel is cut off. 90

5. In an internal combustion engine, in combination, a power cylinder and piston and a scavenging cylinder and piston therefor, arranged in tandem, valve means controlling the flow of air from said scavenging cylinder to said power cylinder, means for controlling the admission of fuel to said power cylinder to drive the engine on fuel, and means for automatically controlling said valve by the admission of air to said scavenging cylinder to drive the engine by compressed air alone when the fuel is cut off. 100

6. In an internal combustion engine having a power cylinder and piston therefor, and an air cylinder and piston therefor, in combination, a manually operated member, mechanism controlled by the first movement of said member for driving said engine with compressed air alone, means controlled by the further movement of said member for driving said engine also by fuel admitted to said power cylinder and mechanism controlled by the further movement of said member for driving the engine by means of fuel alone. 110

7. In an internal combustion engine having a power cylinder and piston therefor, and an air cylinder and piston therefor, in 120

- combination, a manually operated member, mechanism controlled by the first movement of said member for driving said engine with compressed air alone, means controlled by the further movement of said member for driving said engine also by fuel admitted to said power cylinder, mechanism controlled by the further movement of said member for driving the engine by means of fuel alone, and automatic means for cutting off the supply of air to the air cylinder when said member receives said last named further movement.
8. In an internal combustion engine having a power cylinder and piston therefor, and an air cylinder and piston therefor, in combination, a manually operated member, mechanism controlled by the first movement of said member for driving said engine in either direction with compressed air alone, means controlled by the further movement of said member for driving said engine also by fuel admitted to said power cylinder, and mechanism controlled by the further movement of said member for driving the engine by means of fuel alone.
9. In an internal combustion engine having a power cylinder and a piston therefor and an air cylinder and piston therefor, in combination, a manually operated member, an air controlling member actuated by the first movement of said manually operated member, means controlled thereby for admitting air to the air cylinder to drive the engine with compressed air alone, means controlled by the further movement of said manually operated member for driving the engine by fuel admitted to said power cylinder, said air controlling member being arranged to be released from said manually operated member.
10. In an internal combustion engine having a power cylinder and a piston therefor and an air cylinder and piston therefor, in combination, a manually operated member, an air controlling member actuated by the first movement of said manually operated member, means controlled thereby for admitting air to the air cylinder to drive the engine in either direction with compressed air alone, means controlled by the further movement of said manually operated member for driving the engine by fuel admitted to said power cylinder, said air controlling member being arranged to be released from said manually operated member.
11. In an internal combustion engine having a power cylinder and a piston therefor and an air cylinder and a piston therefor, in combination, a manually operated member, an actuator arranged to be moved thereby, an air controlling member in the path of movement of said actuator, means controlled by said air controlling member for admitting air to the air cylinder to drive the engine with compressed air, means controlled by the further movement of said manually operated member for driving the engine by fuel admitted to said power cylinder, said air-controlling member being arranged to move out of the path of movement of said actuator and thereby become released therefrom, and means for actuating the same to cut off the supply of air to said air cylinder.
12. In an internal combustion engine having a power cylinder and a piston therefor and an air cylinder and a piston therefor, in combination, a manually operated member, an actuator arranged to be moved thereby, an air controlling member in the path of movement of said actuator, means controlled by said air controlling member for admitting air to the air cylinder to drive the engine in either direction with compressed air, means controlled by the further movement of said manually operated member for driving the engine by fuel admitted to said power cylinder, said air-controlling member being arranged to move out of the path of movement of said actuator and thereby become released therefrom, means for actuating the same to cut off the supply of air to said air cylinder, and means for preventing an independent reverse movement of said air-controlling member when the engine is running on fuel.
13. In an internal combustion engine having a power cylinder and a piston therefor and an air cylinder and a piston therefor, in combination, a manually operated member, an actuator arranged to be moved thereby, an air controlling member in the path of movement of said actuator, means controlled by said air controlling member for admitting air to the air cylinder to drive the engine in either direction with compressed air, means controlled by the further movement of said manually operated member for driving the engine by fuel admitted to said power cylinder, said air-controlling member being arranged to move out of the path of movement of said actuator and thereby become released therefrom, and means for actuating the same to cut off the supply of air to said air cylinder, said actuator having a part for obstructing an independent reverse movement of said air-controlling member when the engine is running on fuel.
14. In an internal combustion engine having a power cylinder and a piston therefor and an air cylinder and a piston therefor, a hand operated member, mechanism actuated by the first movement of said hand operated member for admitting air to the said air cylinder to drive the engine in either direction with air, means actuated by the further movement of said hand operated member for

admitting fuel to the power cylinder to drive the engine with fuel, and automatic means for preventing a further admission of air to the air cylinder in a way to oppose rotation 5 of the engine in the driving direction.

15. In an internal combustion engine having a power cylinder and a piston therefor and an air cylinder and a piston therefor, a hand operated member, an air-controlling member normally in a neutral position, an actuator arranged to be moved by said hand operated member for actuating said air controlling member, means controlled by said air-controlling member for admitting air 15 to the air-cylinder to drive the engine in either direction, said air-controlling member being arranged to release itself automatically from said actuator, means controlled by the further movement of said hand operated member for driving the engine by fuel admitted to said power cylinder, said hand operated member and said actuator having a connection permitting said further movement of said hand operated member without imparting substantial movement to said actuator, said actuator having a part obstructing a movement of said air-controlling member beyond the said neutral position thereof to prevent independent movement of said air-controlling member in a direction tending to rotate the engine oppositely to the driving direction. 25

30

60

16. In an internal combustion engine having a power cylinder and a piston therefor and an air cylinder and a piston therefor, the combination of a hand operated member, an air-controlling member arranged to be actuated by the first movement of said hand operated member, means controlled by said air-controlling member for admitting air to the air cylinder to drive the engine by air alone, means for admitting fuel to said power cylinder actuated by said hand operated member and arranged to drive the engine simultaneously with fuel and by air, automatic means for cutting off the air supply to the air cylinder during the continued movement of the hand operated member in the same direction, and means for giving an increased fuel supply to the power cylinder by said continued movement of said hand operated member.

17. In an internal combustion engine having a power cylinder and a piston therefor and an air cylinder and a piston therefor, the combination of a hand operated member, an air-controlling member arranged to be actuated by the first movement of said hand operated member, means controlled by said air-controlling member for admitting air to the air cylinder to drive the engine in either direction by air alone, means for admitting fuel to said power cylinder actuated by said hand operated member and

arranged to drive the engine simultaneously with fuel and by air, automatic means for cutting off the air supply to the air cylinder during the continued movement of the hand operated member in the same direction, means for giving an increased fuel supply to the power cylinder by said continued movement of said hand operated member, and means for preventing an independent movement of said air-controlling member in a direction tending to rotate the engine oppositely to the direction in which the engine is running. 65

70

75

18. In an internal combustion engine, in combination, a power cylinder and piston and an air cylinder and piston, a hand operated member for controlling the admission of explosive charges to said power cylinder to drive the engine on fuel, an actuator adapted to be moved by said hand operated member, means controlled thereby for admitting air to the air cylinder to drive the engine by air at the same time that it is driven by the fuel in the power cylinder, and automatic means for cutting off the admission of air when said actuator has arrived at a predetermined point. 80

19. In an internal combustion engine, in combination, a power cylinder and piston and an air cylinder and piston, an air-controlling member, and means controlled thereby to start the engine in either direction with compressed air, hand-operated means for admitting fuel to the power cylinder for driving the engine by fuel while it is being driven on air and including engaging means for engaging said air-controlling member arranged to move said air-controlling member in either direction. 95

20. In an internal combustion engine, in combination, a power cylinder and piston and an air cylinder and piston, an air-controlling member, and means controlled thereby to start the engine in either direction with compressed air, hand-operated means for admitting fuel to the power cylinder for driving the engine by fuel while it is being driven on air and including engaging means for engaging said air-controlling member arranged to move said air-controlling member in either direction, said last means being arranged to release said air-controlling member and shut off the air at a predetermined point. 105

21. In an internal combustion engine, in combination, a power cylinder and piston and an air cylinder and piston, an air-controlling member, and means controlled thereby to start the engine in either direction with compressed air, hand-operated means for admitting fuel to the power cylinder for driving the engine by fuel while it is being driven on air and including engaging means consisting of spring pressed dogs 110

115

120

125

for engaging opposite sides of said air-controlling member arranged to move said air-controlling member in either direction.

22. In an internal combustion engine, in combination, a power cylinder and piston and an air cylinder and piston, hand-operated means for controlling the driving of the engine by fuel admitted to said power cylinder, an actuator adapted to be moved thereby, said actuator having a movable dog, an air-controlling member for controlling the driving of the engine by admitting compressed air to said air cylinder, said air-controlling member lying in the path of said dog when said actuator moves, said dog being arranged to release said air-controlling member after a predetermined movement of said actuator, means for returning said air-controlling member to its "off" position, said dog being yieldingly mounted so as to permit the same to pass said air-controlling member upon the return movement of said actuator.

23. In an internal combustion engine, in combination, a power cylinder and piston and an air cylinder and piston, hand operated means for controlling the driving of the engine with fuel admitted to the power cylinder including a movable actuator, said actuator having a pair of spring pressed dogs, and an air-controlling member disposed between said dogs and adapted to be displaced by the movement of said actuator in either direction, means controlled by said air-controlling member for driving the engine with compressed air admitted to said air cylinder, said actuator having sufficient movement to release said air-controlling member after a predetermined point in the movement of said actuator, said air-controlling member having a neutral point in which no air will be admitted to the air cylinder, means for returning said air-controlling member to said neutral point, said dogs being arranged to yieldingly engage said air-controlling member upon the return movement of said actuator and move aside to permit said actuator to come into its neutral position with said air-controlling member disposed between said dogs.

24. In an internal combustion engine, in combination, a power cylinder and piston and an air cylinder and piston, hand operated means for controlling the driving of the engine with fuel admitted to the power cylinder including a movable actuator, said actuator having a pair of spring pressed dogs, and an air-controlling member disposed between said dogs and adapted to be displaced by the movement of said actuator in either direction, means controlled by said air-controlling member for driving the engine with compressed air admitted to said air cylinder, said actuator having sufficient

movement to release said air-controlling member after a predetermined point in the movement of said actuator, said air-controlling member having a neutral point in which no air will be admitted to the air cylinder, means for returning said air-controlling member to said neutral point, said dogs being arranged to yieldingly engage said air-controlling member upon the return movement of said actuator and move aside to permit said actuator to come into its neutral position with said air-controlling member disposed between said dogs, said actuator having a part in the path of movement of said air-controlling member to prevent a reverse movement of said air-controlling member independently of said actuator beyond the neutral point of said air-controlling member.

25. In an internal combustion engine, in combination a power cylinder and piston, and an air cylinder and piston, a hand wheel for controlling the driving of the engine with fuel admitted to said power cylinder, an actuator adapted to be moved by said wheel, a pair of dogs mounted on said actuator, an air-controlling lever for controlling the driving of the engine by compressed air admitted to said air cylinder, said air-controlling lever having a neutral position lying between said dogs when the engine is still, said actuator dogs being arranged to move said lever in either direction and release said lever after a predetermined movement of said actuator, means for returning said air-controlling lever to its neutral position after its release, said dogs being arranged to yield upon engagement with said lever in the return movement of said actuator and move aside to permit said actuator to come into position with said lever lying between said dogs.

26. In an internal combustion engine, in combination, a power cylinder and piston and an air cylinder and piston, a hand wheel for controlling the driving of the engine by admitting fuel to said power cylinder, an actuator in the form of a slide adapted to be moved by said hand wheel, a pair of spring pressed dogs carried by said actuator, an air controlling lever adapted to swing in either direction, means controlled thereby for driving the engine in either direction by compressed air admitted to said air cylinder, said lever having a neutral position lying between said dogs and arranged to be moved in either direction by one or the other of said dogs, said actuator having a movement in either direction sufficient to release said lever from either of said dogs, and means for returning said lever to its neutral position when the same is released, said dogs being arranged to yieldingly engage said lever upon the re-

turn movement of said actuator and to be displaced thereby to permit said actuator to come into a position in which said lever is between said dogs.

5 27. In an internal combustion engine, in combination, a power cylinder and piston and an air cylinder and piston, a hand wheel for controlling the driving of the engine by fuel admitted to said power cylinder, a member adapted to be rotated by said hand wheel, an actuator in the form of a slide having a pin and slot connection with said member to move said actuator, an air-controlling lever for controlling the driving of 10 the engine by admitting compressed air to said air cylinder, and means carried by said actuator for engaging said lever to move the same.

28. An internal combustion engine embodying a plurality of units each having a power cylinder and a scavenging cylinder with coöperating pistons, passages for establishing communication between adjacent power and scavenging cylinders, fluid-operated valve-means associated with each unit, a compressed air source of supply leading to said passages and valve means, means for operating the same for supplying fuel oil to the power cylinders successively, a manually operable controlling member for admitting compressed air from said source through said valve means and passages direct to the scavenging cylinders successively above their pistons to initially start the engine, and another manually operable controlling member for the fuel supply means, the construction and operation of the parts being such that the compressed air may be admitted to the scavenging cylinders before the pistons in the power cylinders are operated from the combustion fuel oil or while they are so operating, for the purposes specified.

29. An internal combustion engine embodying a plurality of units each having a power cylinder and piston and a scavenging cylinder and piston, the said cylinders and pistons of each unit being arranged in tandem, means for feeding fuel oil to the said power cylinders, a compressed air source of supply, means driven by a moving part of the engine for admitting air from said source to the scavenging cylinders in succession to start the engine, and pneumatically operated valve means for directing into the power cylinders the air compressed in the scavenging cylinders, the construction and arrangements of the parts being such that air from said source may be admitted into a scavenging cylinder while the piston of a power cylinder is being operated through the combustion of a fuel charge for the purposes described.

30. In an internal combustion engine embodying power cylinders and pistons and

scavenging cylinders and pistons, a source of compressed air leading to each of the said scavenging cylinders, fluid actuated valve means associated with each scavenging cylinder for controlling the admission of compressed air thereto to drive the engine ahead or astern, a movable controller member for controlling the operation of the power cylinders and for governing the admission of compressed air to said valve means, the position of said controller determining the direction of rotation of the engine shaft, and an independently operable part for admitting compressed air to said valve means to drive the engine solely by compressed air.

31. In an internal combustion engine embodying power cylinders and pistons and scavenging cylinders and pistons, a source of compressed air leading to each of the said scavenging cylinders, fluid actuated valve means associated with each scavenging cylinder for controlling the admission of compressed air thereto to drive the engine ahead or astern, movable controller mechanism for controlling the operation of the power cylinders and for governing the admission of compressed air to said valve means, the position of said controller mechanism determining the direction of rotation of the engine shaft, said controller mechanism including an independently operable part for admitting compressed air to said valve means to drive the engine solely by compressed air.

32. In an internal combustion engine embodying power cylinders and pistons and scavenging cylinders and pistons, a source of compressed air leading to each of the said scavenging cylinders, fluid actuated valve means associated with each scavenging cylinder for controlling the admission of compressed air thereto to drive the engine ahead or astern, and a movable controller member for admitting fuel to the power cylinder and simultaneously admitting compressed air to said valve means to drive the engine on fuel and simultaneously on compressed air in the scavenging cylinders, the position of said controller determining the direction of rotation of the engine shaft.

33. In an internal combustion engine embodying power cylinders and pistons and scavenging cylinders and pistons, a source of compressed air leading to each of the said scavenging cylinders, fluid actuated valve means associated with each of the scavenging cylinders for controlling the admission of compressed air thereto to drive the engine ahead or astern, a controlling member for controlling the operation of the power cylinders and for controlling the admission of compressed air to said valve means, said controlling member having a movement in

- two directions, and the direction of movement of which determines the direction of rotation of the engine shaft, and an independently operable part for admitting compressed air to said valve means to drive the engine solely by compressed air.
34. In an internal combustion engine embodying power cylinders and pistons and scavenging cylinders and pistons, a source of compressed air leading to each of the said scavenging cylinders, fluid actuated valve means associated with each of the scavenging cylinders for controlling the admission of compressed air thereto to drive the engine ahead or astern, and movable controller mechanism for controlling the operation of the power cylinders and for controlling the admission of compressed air to said valve means, said controller mechanism having movement in two directions, and the direction of movement of which determines the direction of rotation of the engine shaft, said controller mechanism including an independently operable part for admitting compressed air to said valve means to drive the engine solely by compressed air.
35. In an internal combustion engine embodying power cylinders and pistons and scavenging cylinders and pistons, a source of compressed air connected to each of the said scavenging cylinders, fluid actuated valve means associated with each of the scavenging cylinders for controlling the admission of compressed air thereto to drive the engine ahead or astern, a movable controller member for controlling the power cylinders of the engine, and mechanism actuated thereby for controlling the admission of compressed air to drive the engine on compressed air and simultaneously on fuel admitted to the power cylinders.
36. In an internal combustion engine embodying power cylinders and pistons and scavenging cylinders and pistons, a source of compressed air leading to each of said scavenging cylinders, means for feeding fuel oil to the power cylinders, fluid actuated valve means associated with each scavenging cylinder for controlling the admission of compressed air thereto to drive the engine either ahead or astern, a movable controller member for governing the admission of compressed air to said valve means, the position of said controller member determining the direction of rotation of the engine shaft, a connection between the said controller member and the said fuel feeding means for governing the operation of the fuel feeding means, and an independently operable part for admitting compressed air to said valve means to drive the engine solely by compressed air.
37. In an internal combustion engine embodying power cylinders and pistons and scavenging cylinders and pistons, a source of compressed air leading to each of said scavenging cylinders, means for feeding fuel oil to the power cylinders, fluid actuated valve means associated with each scavenging cylinder for controlling the admission of compressed air thereto to drive the engine either ahead or astern, a movable controller member for governing the admission of compressed air to said valve means, the position of said controller member determining the direction of rotation of the engine shaft, a connection between the said controller member and the said fuel feeding means for governing the operation of the fuel feeding means, and an independently operable part for admitting compressed air to said valve means to drive the engine solely by compressed air.
38. In an internal combustion engine embodying power cylinders and pistons and scavenging cylinders and pistons, a source of compressed air leading to each of said scavenging cylinders, means for feeding fuel oil to the power cylinders, fluid actuated valve means associated with each scavenging cylinder for controlling the admission of compressed air thereto to drive the engine either ahead or astern, a movable controller member for governing the admission of compressed air to said valve means, the position of said controller member determining the direction of rotation of the engine shaft, a connection between the said controller member and the said fuel feeding means for governing the operation of the fuel feeding means, arranged to drive the engine on fuel and simultaneously on compressed air admitted to said scavenging cylinders.
39. In an internal combustion engine embodying power cylinders and pistons and scavenging cylinders and pistons, a source of compressed air leading to each one of said scavenging cylinders, valve means associated with each scavenging cylinder for controlling the admission of compressed air thereto to drive the engine either ahead or astern, pumps for feeding fuel oil to the power cylinders, a movable controller member for governing the admission of compressed air through said valve means, the position of said controller determining the direction of rotation of the engine shaft, a lost motion connection between the controller and the fuel feeding pumps for governing the operation of the latter, and an independently operable part for governing the admission of compressed air through said valve means to drive the engine solely by compressed air.
40. In an internal combustion engine embodying power cylinders and pistons and scavenging cylinders and pistons, a source of compressed air leading to each one of said scavenging cylinders, valve means associated with each scavenging cylinder for controlling the admission of compressed air thereto to drive the engine either ahead or astern, pumps for feeding fuel oil to the power cylinders, a movable controller member for governing the admission of compressed air through said valve means, the position of said controller determining the direction of rotation of the engine shaft, a lost motion connection between the controller and the fuel feeding pumps for governing the operation of the latter, and an independently operable part for governing the admission of compressed air through said valve means to drive the engine solely by compressed air.

- with each scavenging cylinder for controlling the admission of compressed air thereto to drive the engine either ahead or astern, pumps for feeding fuel oil to the power cylinders, and movable controller mechanism for governing the admission of compressed air through said valve means, the position of said controller determining the direction of rotation of the engine shaft, a 5 lost motion connection between the controller and the fuel feeding pumps for governing the operation of the latter, said controller mechanism including an independently movable part for governing the 10 admission of compressed air through said valve means to drive the engine solely by compressed air.

41. In an internal combustion engine embodying power cylinders and pistons and 20 scavenging cylinders and pistons, a source of compressed air leading to each one of said scavenging cylinders, valve means associated with each scavenging cylinder for controlling the admission of compressed air thereto to 25 drive the engine either ahead or astern, pumps for feeding fuel oil to the power cylinders, a movable controller member for governing the admission of compressed air through said valve means, the position of 30 said controller determining the direction of rotation of the engine shaft, a lost motion connection between the controller and the fuel feeding pumps for governing the operation of the latter arranged to drive the 35 engine on fuel and simultaneously on compressed air.

42. In an internal combustion engine of the Diesel type embodying power cylinders and pistons and scavenging cylinders and pistons, a source of compressed air leading to 40 each of the scavenging cylinders, means for feeding fuel oil to the power cylinders, fluid-actuated valve means associated with each scavenging cylinder for controlling the admission of compressed air thereto to initially start the engine under compressed air power, a movable controller member for governing the admission of compressed air through 45 said valve means to the scavenging cylinders, and for admitting the charge of fuel oil to the power cylinders, means actuated by said controller member for controlling the operation of the fuel feeding means, and an independently operable part for governing the admission of compressed air to the 50 scavenging cylinders to drive the engine solely by compressed air.

43. In an internal combustion engine of the Diesel type embodying power cylinders and pistons and scavenging cylinders and pistons, a source of compressed air leading to 60 each of the scavenging cylinders, means for feeding fuel oil to the power cylinders, fluid-actuated valve means associated with each scavenging cylinder for controlling the admission of compressed air thereto to initially start the engine under compressed air power, movable controller mechanism for governing the admission of compressed air through said valve means to the scavenging cylinders, and for admitting the charge of fuel oil to the power cylinders, means actuated by said controller mechanism for controlling the operation of the fuel feeding means, said last means being thrown into operation by the controller after the latter has moved past the compressed air admission position, and an independently operable part for governing the admission of compressed air to the 65 scavenging cylinders to drive the engine solely by compressed air.

admission of compressed air thereto to initially start the engine under compressed air power, movable controller mechanism for governing the admission of compressed air through said valve means to the scavenging cylinders, and for admitting the charge of fuel oil to the power cylinders, means actuated by said controller mechanism for controlling the operation of the fuel feeding means, said controlling mechanism including an independently operable part for governing the admission of compressed air to the scavenging cylinders to drive the engine solely by compressed air.

44. In an internal combustion engine of 80 the Diesel type embodying power cylinders and pistons and scavenging cylinders and pistons, a source of compressed air leading to each of the scavenging cylinders, means for feeding fuel oil to the power cylinders, 85 fluid-actuated valve means associated with each scavenging cylinder for controlling the admission of compressed air thereto to initially start the engine under compressed air power, a movable controller member for 90 governing the admission of compressed air through said valve means to the scavenging cylinders, and for admitting the charge of fuel oil to the power cylinders, means actuated by said controller member for controlling the operation of the fuel feeding means, arranged to drive the engine on fuel and simultaneously on compressed air admitted to the scavenging cylinders.

45. In an internal combustion engine of 100 the Diesel type embodying power cylinders and pistons and scavenging cylinders and pistons, a source of compressed air leading to each of the scavenging cylinders, means for feeding fuel oil to the power cylinders, 105 fluid-actuated valve means associated with each scavenging cylinder for controlling the admission of compressed air thereto to initially start the engine under compressed air power, a movable controller member governing 110 the admission of compressed air through said valve means to the scavenging cylinders for governing the admission of the charge of fuel to the power cylinders, and means actuated by said controller member for controlling the operation of the fuel feeding means, said last means being thrown into operation by the controller after the latter has moved past the compressed air admission position, and an independently operable part for controlling the admission of compressed air to 115 drive the engine solely by compressed air.

46. In an internal combustion engine of the Diesel type embodying power cylinders and pistons and scavenging cylinders and pistons, a source of compressed air leading to each of the scavenging cylinders, means for feeding fuel oil to the power cylinders, 120 fluid-actuated valve means associated with each scavenging cylinder for controlling the admission of compressed air thereto to initially start the engine under compressed air power, movable controller mechanism for governing the admission of compressed air through said valve means to the scavenging cylinders, and for admitting the charge of fuel oil to the power cylinders, means actuated by said controller mechanism for controlling the operation of the fuel feeding means, said last means being thrown into operation by the controller after the latter has moved past the compressed air admission position, and an independently operable part for governing the admission of compressed air to 125 drive the engine solely by compressed air.

admission of compressed air thereto to initially start the engine under compressed air power, movable controller mechanism governing the admission of compressed air through said valve means to the scavenging cylinders for governing the admission of the charge of fuel to the power cylinders, and means actuated by said controller mechanism for controlling the operation of the fuel feeding means, said actuated means being thrown into operation by the controller after the latter has moved past the compressed air admission position, said controller mechanism including an independently operable part for controlling the admission of compressed air to drive the engine solely by compressed air.

47. In an internal combustion engine of the Diesel type embodying power cylinders and pistons and scavenging cylinders and pistons, a source of compressed air leading to each of the scavenging cylinders, means for feeding fuel oil to the power cylinders, fluid actuated valve means associated with each scavenging cylinder for controlling the admission of compressed air thereto to initially start the engine under compressed air power, a movable controller member governing the admission of compressed air through said valve means to the scavenging cylinders for governing the admission of the charge of fuel to the power cylinders, and means actuated by said controller member for controlling the operation of the fuel feeding means, said actuated means being thrown into operation by the controller after the latter has moved past the compressed air admission position, and arranged to drive the engine on fuel and simultaneously on compressed air admitted to the scavenging cylinders.

48. In an internal combustion engine of the Diesel type embodying power cylinders and pistons and scavenging cylinders and pistons, a source of compressed air leading to each of said scavenging cylinders, means for feeding fuel oil to said power cylinders, valve means associated with each scavenging cylinder for controlling the admission of compressed air thereto to drive the engine either ahead or astern, a movable controller member governing the admission of compressed air through said valve means to the scavenging cylinders, and for governing the admission of fuel oil to the power cylinders, means actuated by said controller after the latter has moved past the compressed air admission position for setting the fuel feeding means in operation, and an independently operable part for controlling the admission of compressed air to the scavenging cylinders to drive the engine solely by compressed air.

49. In an internal combustion engine of the Diesel type embodying power cylinders

and pistons and scavenging cylinders and pistons, a source of compressed air leading to each of said scavenging cylinders, valve means associated with each scavenging cylinder for controlling the admission of compressed air thereto to drive the engine either ahead or astern, movable controller mechanism governing the admission of compressed air through said valve means to the scavenging cylinders, and for governing the admission of fuel oil to the power cylinders, means actuated by said controller mechanism after the latter has moved past the compressed air admission position for setting the fuel feeding means in operation, said controller mechanism including an independently operable part for controlling the admission of compressed air to the scavenging cylinders to drive the engine solely by compressed air.

50. In an internal combustion engine of the Diesel type embodying power cylinders and pistons and scavenging cylinders and pistons, a source of compressed air leading to each of said scavenging cylinders, means for feeding fuel oil to said power cylinders, valve means associated with each scavenging cylinder for controlling the admission of compressed air thereto to drive the engine either ahead or astern, a movable controller member governing the admission of compressed air through said valve means to the scavenging cylinders, and for governing the admission of fuel oil to the power cylinders, and means actuated by said controller after the latter has moved past the compressed air admission position for setting the fuel feeding means in operation arranged to drive the engine on fuel and simultaneously on compressed air admitted to the scavenging cylinders.

51. In an internal combustion engine embodying power cylinders and pistons and scavenging cylinders and pistons, a source of compressed air leading to each of said scavenging cylinders, plunger pumps for feeding fuel oil to the power cylinders, valve means associated with each scavenging cylinder for controlling the admission of compressed air thereto to initially start the engine, a movable controller member for governing the admission of compressed air through said valve means to the scavenging cylinders, means actuated by the controller member for determining the length of stroke of the fuel feeding plungers, and an independently operable part for controlling the admission of compressed air to the scavenging cylinders to drive the engine solely by compressed air.

52. In an internal combustion engine embodying power cylinders and pistons and scavenging cylinders and pistons, a source of compressed air leading to each of said scavenging cylinders, plunger pumps for feeding fuel oil to the power cylinders, valve

- means associated with each scavenging cylinder for controlling the admission of compressed air thereto to initially start the engine, movable controller mechanism for governing the admission of compressed air through said valve means to the scavenging cylinders, means actuated by the controller mechanism for determining the length of stroke of the fuel feeding plungers, said controller mechanism including an independently operable part for controlling the admission of compressed air to the scavenging cylinders to drive the engine solely by compressed air. 65
- 5 15 53. In an internal combustion engine embodying power cylinders and pistons and scavenging cylinders and pistons, a source of compressed air leading to each of said scavenging cylinders, plunger pumps for feeding fuel oil to the power cylinders, valve means associated with each scavenging cylinder for controlling the admission of compressed air thereto to initially start the engine, a movable controller member for governing the admission of compressed air through said valve means to the scavenging cylinders, means actuated by the controller member for determining the length of stroke of the fuel feeding plungers, said controller member being arranged to effect the driving of the engine on fuel and simultaneously on compressed air admitted to the scavenging cylinders. 70

- ently operable part for effecting the admission of compressed air to the scavenging cylinders to drive the engine solely by compressed air.
- 5 59. In an internal combustion engine of the Diesel type embodying power cylinders and pistons and scavenging cylinders and pistons, a source of compressed air leading to each of said scavenging cylinders, means for feeding fuel oil to the power cylinders including variable means for varying the charge of fuel oil fed to said power cylinders, valve means associated with each scavenging cylinder for controlling the admission of compressed air thereto to initially start the engine, a movable controller member for governing the admission of compressed air to said valve means, a lost motion connection between said controller and the said variable means for actuating the latter, arranged to drive the engine on fuel and simultaneously on compressed air admitted to the said scavenging cylinders.
- 10 60. In an internal combustion engine of the Diesel type embodying power cylinders and pistons and scavenging cylinders and pistons, a valve controlled atomizer for each power cylinder, a pair of valve actuators for each of the valve controlled atomizers, means for feeding fuel oil to the power cylinders, a controller member common to both said fuel feeding means and said valve actuators, an independently operable part, and means actuated thereby for admitting compressed air to the scavenging cylinders to drive the engine solely by compressed air.
- 15 61. In an internal combustion engine of the Diesel type embodying power cylinders and pistons and scavenging cylinders and pistons, a valve controlled atomizer for each power cylinder, a pair of valve actuators for each of the valve controlled atomizers, means for feeding fuel oil to the power cylinders, controller mechanism common to both said fuel feeding means and said valve actuators, said controlling mechanism including an independently operable part, and means actuated thereby for admitting compressed air to the scavenging cylinders to drive the engine solely by compressed air.
- 20 62. In an internal combustion engine of the Diesel type embodying power cylinders and pistons and scavenging cylinders and pistons, a valve controlled atomizer for each power cylinder, a pair of valve actuators for each of the valve controlled atomizers, means for feeding fuel oil to the power cylinders, a controller member common to both said fuel feeding means and said valve actuators, arranged to admit compressed air to the scavenging cylinders and simultaneously admit fuel to the power cylinders to drive the engine at the same time on fuel and compressed air.
- 25 63. In an internal combustion engine of the Diesel type embodying power cylinders and pistons and scavenging cylinders and pistons, a source of compressed air leading to each of said scavenging cylinders, valved atomizers for each power cylinder, means for feeding fuel oil to the said atomizers, a pair of cam operated valve actuators for each atomizer, a movable controller member common to both said fuel feeding means and said valve actuators, an independently operable part and means actuated thereby for admitting compressed air to the scavenging cylinders to drive the engine solely by compressed air.
- 30 64. In an internal combustion engine of the Diesel type embodying power cylinders and pistons and scavenging cylinders and pistons, a source of compressed air leading to each of said scavenging cylinders, a valved atomizer for each power cylinder, means for feeding fuel oil to the said atomizers, a pair of cam operated valve actuators for each atomizer, movable controller mechanism common to both said fuel feeding means and said valve actuators, said controller mechanism including an independently operable part and means actuated thereby for admitting compressed air to the scavenging cylinders to drive the engine solely by compressed air.
- 35 65. In an internal combustion engine of the Diesel type embodying power cylinders and pistons and scavenging cylinders and pistons, a source of compressed air leading to each of said scavenging cylinders, a valved atomizer for each power cylinder, means for feeding fuel oil to the said atomizers, a pair of cam operated valve actuators for each atomizer, a movable controller member common to both said fuel feeding means and said valve actuators, arranged to admit fuel to the engine to drive the engine on fuel and simultaneously on compressed air admitted to the scavenging cylinders.
- 40 66. In an internal combustion engine of the Diesel type embodying power cylinders and scavenging cylinders and pistons, a source of compressed air leading to each of said scavenging cylinders, a valve controlled atomizer for each power cylinder, a pair of valve actuators for each atomizer, means for feeding fuel oil to the said atomizer including variable means for varying the charge of fuel oil so fed, valve means associated with each scavenging cylinder for controlling the admission of compressed air thereto to initially start the engine, a movable controller member for governing the admission of compressed air to said valve means, a connection between said controller member and the said variable means for actuating the latter, a separate connection between the said controller member and the

said atomizer valve actuators, and an independently operable part for governing the admission of compressed air to said valve means to drive the engine solely by compressed air.

67. In an internal combustion engine of

- the Diesel type embodying power cylinders and scavenging cylinders and pistons, a source of compressed air leading to each of said scavenging cylinders, a valve controlled atomizer for each power cylinder, a pair of valve actuators for each atomizer, means for feeding fuel oil to the said atomizer including variable means for varying the charge of fuel oil so fed, valve means associated with each scavenging cylinder for controlling the admission of compressed air thereto to initially start the engine, controller mechanism for governing the admission of compressed air to said valve means, a connection between said controller mechanism and the said variable means for actuating the latter, a separate connection between the said controller mechanism and the said atomizer valve actuators, said controller mechanism including an independently operable part for governing the admission of compressed air to said valve means to drive the engine solely by compressed air.

68. In an internal combustion engine of the Diesel type embodying power cylinders and pistons and scavenging cylinders and pistons, an atomizer for each power cylinder, a pair of cam actuated valve actuators for each atomizer, separate cams for actuating said cam actuators, means for feeding fuel oil to the atomizers including variable means for varying the charge of fuel oil so fed, a source of compressed air leading to each of the scavenging cylinders, valve means associated with each scavenging cylinder for controlling the admission of compressed air thereto to initially start the engine, a movable controller member for governing the admission of compressed air to said valve means, separate connections between said controller member and said variable oil feeding means and the said valve means respectively, and an independently operable part for controlling the admission of compressed air to the scavenging cylinders to drive the engine solely by compressed air.

69. In an internal combustion engine of the Diesel type embodying power cylinders and pistons and scavenging cylinders and pistons, an atomizer for each power cylinder, a pair of cam actuated valve actuators for each atomizer, separate cams for actuating said cam actuators, means for feeding fuel oil to the atomizers including variable means for varying the charge of fuel oil so fed, a source of compressed air leading to each of the scavenging cylinders, valve means associated with each scavenging cylinder for controlling the admission of com-

pressed air thereto to initially start the engine, movable controller mechanism for governing the admission of compressed air to said valve means, separate connections between said controller mechanism and said variable oil feeding means and the said valve means respectively, said controller mechanism including an independently operable part for controlling the admission of compressed air to the scavenging cylinders to drive the engine solely by compressed air.

70. In an internal combustion engine of

- the Diesel type embodying power cylinders and pistons and scavenging cylinders and pistons, an atomizer for each power cylinder, a pair of cam actuated valve actuators, means for feeding fuel oil to the atomizers including variable means for varying the charge of fuel oil so fed, a source of compressed air leading to each of the scavenging cylinders, valve means associated with each scavenging cylinder for controlling the admission of compressed air thereto to initially start the engine, a movable controller member for governing the admission of compressed air to said valve means, separate connections between said controller member and said variable oil feeding means and the said valve means respectively, arranged to drive the engine on fuel and simultaneously on compressed air admitted to the scavenging cylinders.

71. In an internal combustion engine of the Diesel type embodying power cylinders and pistons and scavenging cylinders and pistons, a valve controlled passage for establishing communication between each of said power and scavenging cylinders, a fluid actuated valve normally closing each passage, a pair of fluid actuated valves associated with each of the aforesaid valves for controlling the operation of the latter to drive the engine either ahead or astern, a source of compressed air, a separate valve controlled conduit leading from said source to each of the said pair of valves, a manually operable controller member, means operated thereby for controlling the admission of compressed air into one or the other of said conduits respectively, and for controlling the operation of the power cylinders, and an independently operable part for controlling the admission of compressed air to said conduits for driving the engine solely by compressed air.

72. In an internal combustion engine of the Diesel type embodying power cylinders and pistons and scavenging cylinders and pistons, a valve controlled passage for establishing communication between each of the said power and scavenging cylinders, a fluid actuated valve normally closing each passage, a pair of fluid actuated valves associated with each of the aforesaid valves for controlling the operation of the latter to 130 125

- drive the engine either ahead or astern, a source of compressed air, a separate valve controlled conduit leading from said source to each of the said pair of valves, manually operable controller mechanism, means operated thereby for controlling the admission of compressed air into one or the other of said conduits respectively, and for controlling the operation of the power cylinders, said controller mechanism including an independently operable part for controlling the admission of compressed air to said conduits for driving the engine solely by compressed air.
73. In an internal combustion engine of the Diesel type embodying power cylinders and pistons and scavenging cylinders and pistons, a valve controlled passage for establishing communication between each of the said power and scavenging cylinders, a fluid actuated valve normally closing each passage, a pair of fluid actuated valves associated with each of the aforesaid valves for controlling the operation of the latter to drive the engine either ahead or astern, a source of compressed air, a separate valve controlled conduit leading from said source to each of said pair of valves, a manually operable controller member, means operated thereby for controlling the admission of compressed air into one or the other of said conduits respectively, and for controlling the operation of the power cylinders, arranged to drive the engine on fuel and simultaneously on compressed air admitted to the scavenging cylinders.
74. In an internal combustion engine of the Diesel type embodying power cylinders and pistons and scavenging cylinders and pistons, a valve controlled passage for establishing communication between each of the said power and scavenging cylinders, a fluid actuated valve normally closing each passage, a pair of fluid actuated valves associated with each of the aforesaid valves for controlling the operation of the latter to drive the engine either ahead or astern, a source of compressed air, a valve box to which said source leads, separate conduits leading from said valve box to the said pair of valves respectively, separate throttle valves in said valve box for controlling the passage of compressed air to said conduits, a manually operable controller for actuating said throttle valves, means actuated thereby for controlling the operation of the power cylinders, and an independently operable part for actuating said throttle valves to drive the engine solely by compressed air.
75. In an internal combustion engine of the Diesel type embodying power cylinders and pistons and scavenging cylinders and pistons, a valve controlled passage for establishing communication between each of the said power and scavenging cylinders, a fluid actuated valve normally closing each passage, a pair of fluid actuated valves associated with each of the aforesaid valves for controlling the operation of the latter to drive the engine either ahead or astern, a source of compressed air, a valve box to which said source leads, separate conduits leading from said valve box to the said pair of valves respectively, separate throttle valves in said valve box for controlling the passage of compressed air to said conduits, a manually operable controller member for actuating said throttle valves, said controller member being movable in two directions and the direction of movement determining the particular throttle valve to be actuated, means actuated by said controller member for controlling the operation of the power cylinders, said controller mechanism including an independently operable part for actuating said throttle valves to drive the engine solely by compressed air.
76. In an internal combustion engine of the Diesel type embodying power cylinders and pistons and scavenging cylinders and pistons, a valve controlled passage for establishing communication between each of the said power and scavenging cylinders, a fluid actuated valve normally closing each passage, a pair of fluid actuated valves associated with each of the aforesaid valves for controlling the operation of the latter to drive the engine either ahead or astern, a source of compressed air, a valve box to which said source leads, separate conduits leading from said valve box to the said pair of valves respectively, separate throttle valves in said valve box for controlling the passage of compressed air to said conduits, a manually operable controller for actuating said throttle valves, means actuated thereby for controlling the operation of the power cylinders, and arranged to drive the engine on fuel and simultaneously on compressed air admitted to the scavenging cylinders.
77. In an internal combustion engine of the Diesel type embodying power cylinders and pistons and scavenging cylinders and pistons, a valve controlled passage for establishing communication between each of the said power and scavenging cylinders, a fluid actuated valve normally closing each passage, a pair of fluid actuated valves associated with each of the aforesaid valves for controlling the operation of the latter to drive the engine either ahead or astern, a source of compressed air, a valve box to which said source leads, separate conduits leading from said valve box to said pairs of valves respectively, separate throttle valves in said valve box for controlling the passage of compressed air to said conduits, a manually operable controller member for actuating said throttle valves, said controller member being movable in two directions and the direction of movement determining the particular throttle valve to be actuated, means actuated by said controller member for controlling the operation of the power cylinders, said controller mechanism including an independently operable part for actuating said throttle valves to drive the engine solely by compressed air.

cylinders, and an independently operable part for actuating said throttle valves to drive the engine solely by compressed air.

78. In an internal combustion engine of the Diesel type embodying power cylinders and pistons and scavenging cylinders and pistons, a valve controlled passage for establishing communication between said power and scavenging cylinders, a fluid actuated valve normally closing each passage, a pair of fluid actuated valves associated with each of the aforesaid valves for controlling the operation of the latter to drive the engine either ahead or astern, a source of compressed air, a valve box to which said source leads, separate conduits leading from said valve box to said pairs of valves respectively, separate throttle valves in said valve box for controlling the passage of compressed air to said conduits, manually operable controller mechanism for actuating said throttle valves, said controller mechanism being movable in two directions and the direction of movement determining the particular throttle valve to be actuated, means actuated by said controller mechanism for controlling the operation of the power cylinders, said controller mechanism including an independently operable part for actuating said throttle valves to drive the engine solely by compressed air.

79. In an internal combustion engine of the Diesel type embodying power cylinders and pistons and scavenging cylinders and pistons, a valve controlled passage for establishing communication between the said power and scavenging cylinders, a fluid actuated valve normally closing each passage, a pair of fluid actuated valves associated with each of the aforesaid valves for controlling the operation of the latter to drive the engine either ahead or astern, a source of compressed air, a valve box to which said source leads, separate conduits leading from said valve box to said pairs of valves respectively, separate throttle valves in said valve box for controlling the passage of compressed air to said conduits, a manually operable controller member for actuating said throttle valves, said controller member being movable in two directions and the direction of movement determining the particular throttle valve to be actuated, means actuated by said controller member for controlling the operation of the power cylinders, arranged to drive the engine on fuel and simultaneously on compressed air admitted to the scavenging cylinders.

80. In an internal combustion engine of the Diesel type embodying power cylinders and pistons and scavenging cylinders and pistons, a valve controlled atomizer for each of the power cylinders, a pair of levers for operating each of said atomizers, variable cam operated means for actuating each of said levers, variable means for feeding fuel

oil to each of said atomizers, air admitting mechanism for controlling the admission of compressed air to said scavenging cylinders to operate the engine as a motor, and a manually operable controller having independent connections respectively with said variable oil feeding means and said variable lever actuating means, said controller having an independently operable member for actuating said air admitting mechanism.

81. In an internal combustion engine of the Diesel type embodying power cylinders and pistons and scavenging cylinders and pistons, a fuel admission valve for each power cylinder, means for feeding fuel to said admission valves, a cam operated valve actuator for each admission valve, air admitting mechanism for controlling the admission of air to said scavenging cylinders to drive the engine on compressed air as a motor, and a manual controller having separate operative connections respectively with said fuel feeding means and said valve actuators, said controller including an independently movable member for actuating said air admitting mechanism.

82. An internal combustion engine of the Diesel type embodying a power cylinder and piston and a scavenging cylinder and piston of larger diameter than, and arranged in tandem with the power cylinder, a valve controlled passage leading from the upper end of the scavenging cylinder through a side wall of the power cylinders, said passage having an inlet, a fluid-actuated valve in said passage, said valve having two seating positions, one of which normally closes the passage to both cylinders but permits the valve to open under impulses of scavenging air from the scavenging cylinder during normal operation of the engine, and the other of which cuts off communication with the power cylinder but permits starting air entering the said inlet to said passage to pass into the scavenging cylinder above its piston for starting the engine initially under compressed air power, a source of compressed air leading to said inlet, a valve for controlling the admission of compressed air to said inlet, manually controlled means for admitting fuel to the power cylinders to drive the engine on fuel, and independently manually operable means for controlling said last valve.

83. In an internal combustion engine of the Diesel type embodying a power cylinder and piston and a scavenging cylinder and piston, a cam shaft with a cam thereon, a valve controlled passage for establishing communication between said cylinders, a fluid actuated valve normally closing said passage, a compressed air source, a conduit leading from said source to said valve controlled passage, a valve in said conduit, said last named valve having a stem, one end of

which is adapted to be engaged by the cam on the cam shaft to move the valve from its seat, mechanism for admitting fuel to the power cylinders to drive the engine on fuel, 5 manually operated means for controlling said fuel admitting mechanism, and independently operable manually controlled means for admitting compressed air from said source to said conduit to hold the said 10 last named valve in elevated position to be engaged by its cam.

84. In a reversible internal combustion engine of the compression type embodying power cylinders and pistons, and scavenging cylinders and pistons, an atomizer valve associated with each power cylinder, pumping means for feeding fuel oil to the said valves, means for actuating the said valves, air starting means, a single manually operable controller having movement in two directions, and separate operative connections respectively between said controller and said pumping means, air starting means and valve actuating means, whereby movement 25 of the controller in either direction will set all said means for operation, said controller having an independently movable member for independently controlling said air-starting means.

85. In an internal combustion engine of the Diesel type embodying power cylinders and pistons and scavenging cylinders and pistons, an atomizer valve associated with each power cylinder, pumping means for feeding fuel oil to the said valves, means for actuating the said valves, air starting means, a single manually operable controller having separate operative connections respectively with said pumping means, said 35 valve actuating means and said air starting means, whereby all of the said means may be set for operation by the one controller, and an independently operable controlling member for independently controlling said air 40 starting means.

86. In an internal combustion engine embodying power cylinders and pistons, and air cylinders and pistons, the combination of an air admission valve for controlling 50 the admission of air to the air cylinder to drive the engine as an air motor, a mechanically operated member for periodically actuating said valve to admit the air at the proper time to the cylinder, said valve being arranged so that the admission of air thereto moves said valve into mechanical coöperation with said member, mechanism for admitting fuel to said power cylinders to drive the engine on fuel, and a hand operated controlling member for actuating 55 said last named mechanism and for admitting compressed air to said valve to drive the engine simultaneously on fuel in the power cylinders, and on compressed air admitted to the air cylinders.

87. In an internal combustion engine embodying power cylinders and pistons, and air cylinders and pistons, the combination of an air-admission valve for controlling the admission of air to the air cylinder to 70 drive the engine as an air motor, mechanical driving mechanism driven by a moving part of the engine for periodically actuating said valve to admit air at the proper time to the cylinder, pneumatic means for bringing 75 said valve and said valve driving mechanism into mechanical coöperation, mechanism for admitting fuel to said power cylinders to drive the engine on fuel, and a hand operated controlling member for actuating 80 said last named mechanism and for controlling said pneumatic means to bring the said valve and said mechanical driving mechanism into coöperative relation to drive the engine simultaneously on fuel in 85 the power cylinders and on compressed air admitted to the air cylinders.

88. In an internal combustion engine embodying power cylinders and pistons and air cylinders and pistons, the combination of an air admission valve for controlling the admission of air to each air cylinder to drive the engine as an air motor, a valve chest for each admission valve having an 90 inlet port closed by said valve until air is admitted through said port, said valve chest having an outlet port for conducting the air from said chest to each air cylinder to operate the air piston therein, mechanism for admitting fuel to said power cylinders to 95 drive the engine on fuel, hand operated controlling mechanism for actuating said last named mechanism and for independently admitting air through said inlet port to force said valve against said outlet port, and 100 mechanical driving mechanism driven by a moving part of the engine for periodically actuating said valve to open said outlet port and admit air at the proper time to the cylinder, to drive the engine solely on 105 compressed air.

89. In an internal combustion engine embodying power cylinders and pistons, and air cylinders and pistons, the combination of an air-admission valve for controlling 115 the admission of air to each air cylinder to drive the engine as an air motor, mechanical driving mechanism driven by a moving part of the engine for periodically actuating the valves to admit air at the proper 120 time to the cylinders, pneumatic means for bringing the valves and said valve driving mechanism into mechanical coöperation, mechanism for admitting fuel to said power cylinders to drive the engine on fuel, and a hand operated controlling mechanism for actuating 125 said last named mechanism and having means for independently controlling said pneumatic means to bring the valves and said mechanical driving mechanism into coöp- 130

erative relation to drive the engine solely by compressed air admitted to the air cylinders.

90. In an internal combustion engine embodying power cylinders and pistons and scavenging cylinders and pistons, valve controlled passages leading to the said power cylinders and to the said scavenging cylinders, a fluid-actuated valve corresponding to each power cylinder and its scavenging cylinder for controlling said passages, a source of compressed air, a throttle valve in the form of a check valve opening toward the source of compressed air for admitting compressed air to said fluid actuated valve for driving the engine solely by compressed air, means for supplying fuel to said power cylinders to drive the engine solely by fuel, or simultaneously on fuel in the power cylinders and on compressed air admitted to the scavenging cylinders.

91. In an internal combustion engine embodying power cylinders and pistons and scavenging cylinders and pistons, an air manifold, a scavenging passage leading from said air manifold to each of said power cylinders, an air passage leading from each of said scavenging cylinders toward said air manifold, fluid-controlled valves for controlling the flow of scavenging air from said scavenging cylinders into said air manifold when the engine is driven solely on fuel admitted to said power cylinders and when the engine is driven by compressed air admitted to said scavenging cylinders, a controller device, means actuated thereby for driving the engine solely on fuel admitted to said power cylinders, valve controlling means actuated by said controller device for controlling said valves to start the engine initially on compressed air admitted to said scavenging cylinders and arranged to drive the engine simultaneously on fuel admitted to said power cylinders, and on compressed air admitted to said scavenging cylinders.

92. In an internal combustion engine embodying power cylinders and pistons and scavenging cylinders and pistons, an air manifold, a scavenging passage leading from said air manifold to each of said power cylinders, an air passage leading from each of said scavenging cylinders toward said air manifold, fluid-controlled valves for controlling the flow of scavenging air from said scavenging cylinders into said air manifold when the engine is driven solely on fuel admitted to said power cylinders and when the engine is driven by compressed air admitted to said scavenging cylinders, a controller device, means actuated thereby for driving the engine solely on fuel admitted to said power cylinders, valve controlling means actuated by said controller device for controlling said valves

to start the engine initially on compressed air admitted to said scavenging cylinders, and arranged to drive the engine simultaneously on fuel admitted to said power cylinders and on compressed air admitted to said scavenging cylinders, said valve controlling means including a throttle valve actuated by said controller device for admitting compressed air to the engine, said throttle valve being in the form of a check valve opening toward the source of compressed air so as to permit a backward flow of air toward the source of compressed air, said fluid-operated valve affording means for operating said scavenging cylinders as air compressing cylinders when fluid is admitted to said power cylinders.

93. In an internal combustion engine of the Diesel type embodying power cylinders and scavenging cylinders and pistons, a source of compressed air leading to each of said scavenging cylinders, a valve controlled atomizer for each power cylinder, a pair of valve actuators for each atomizer, means for feeding fuel oil to the said atomizer including variable means for varying the charge of fuel oil so fed, valve means associated with each scavenging cylinder for controlling the admission of compressed air thereto to initially start the engine, a movable controller member for governing the admission of compressed air to said valve means, a connection between said controller member and the said variable means for actuating the latter, a separate connection between the said controller member and the said atomizer valve actuators, arranged to drive the engine by fuel in the power cylinders, and simultaneously by compressed air in the scavenging cylinders.

94. In an internal combustion engine, embodying power cylinders and pistons and scavenging cylinders and pistons arranged in tandem, with passages for establishing communication between the power and scavenging cylinders, valve means for controlling the passage of air leading to and coming from each scavenging cylinder, comprising a rotary valve and fluid-actuated means for rotating said valve to admit starting air to a scavenging cylinder and to allow for the passage of scavenging air from that cylinder to a power cylinder.

95. In an engine having fuel operated power cylinders and air cylinders for driving the engine on compressed air, in combination, a hand operated member, means actuated thereby for effecting the driving of the power cylinders on fuel, and means also actuated thereby including an independently movable part for admitting compressed air to the air cylinders for driving the engine solely by compressed air in the air cylinders.

96. In an internal combustion engine em-

- bodying power cylinders and scavenging cylinders and pistons arranged in tandem, with passages for establishing connection between the power cylinders and scavenging cylinders, valve means for controlling said passages to permit air to flow to and from each scavenging cylinder, actuating means including a fluid actuated piston independent of but connected with said valve 5
- means for actuating said valve means to admit starting air to a scavenging cylinder, and to allow the passage of scavenging air from said cylinder for scavenging a power cylinder. 10
- 15 97. In an internal combustion engine embodying power cylinders and scavenging cylinders and pistons arranged in tandem, with passages for establishing connection between the power and scavenging cylinders, a rotary valve for controlling said passages to permit air to flow to and from each scavenging cylinder, actuating means therefor including a fluid actuated piston, said valve having a lever for rotating the 20 same connected with said fluid actuated piston to enable said fluid actuated piston to actuate said rotary valve, and means for admitting compressed air against said fluid actuated piston to actuate said rotary valve. 25
- 30 98. In an internal combustion engine embodying power cylinders and scavenging cylinders and pistons arranged in tandem, with passages for establishing connection between the power and scavenging cylinders, a rotary valve for controlling said passages to permit air to flow to and from each scavenging cylinder, actuating means therefor including a fluid actuated piston, said valve having a lever for rotating the 35 same connected with said fluid actuated piston to enable said fluid actuated piston to actuate said rotary valve, and means for admitting compressed air against said fluid actuated piston to actuate said rotary valve. 40
- 45 99. In an internal combustion engine embodying power cylinders and scavenging cylinders and pistons arranged in tandem, with passages for establishing connection between the power and scavenging cylinders, a rotary valve for controlling said passages to permit air to flow to and from each scavenging cylinder, actuating means therefor including a fluid actuated piston, said valve having a lever for rotating the 50 same connected with said fluid actuated piston to enable said fluid actuated piston to actuate said rotary valve, and means for admitting compressed air against said fluid actuated piston to actuate said rotary valve, said engine having a port arranged so as to be uncovered by a movement of said fluid actuated piston to admit compressed air to said rotary valve. 55
- 60 100. In an internal combustion engine embodying power cylinders and scavenging cylinders and pistons arranged in tandem, with passages for establishing connection between the power and scavenging cylinders, a rotary valve for controlling said passages to permit air to flow to and from each scavenging cylinder, actuating means therefor including a fluid actuated piston, said valve having a lever for rotating the 65 same connected with said fluid actuated piston to enable said fluid actuated piston to actuate said rotary valve, means for admitting compressed air against said fluid actuated piston to actuate said rotary valve, and a cut-off valve for admitting compressed air to said fluid actuated piston. 70
- 75 101. In an internal combustion engine, in combination, power cylinders and scavenging cylinders and pistons arranged in tandem, an air manifold, said engine having passages for admitting compressed air to said scavenging cylinders and for establishing communication between the manifold and the scavenging cylinders and between the manifold and the power cylinders, a rotary valve for controlling said passages to permit starting air to flow to each scavenging cylinder and to permit air to flow to 80 the manifold from the scavenging cylinders, actuating means including a fluid-actuated piston connected with said rotary valve to actuate the same to control said passages, a cut-off valve, a seat with which said valve co-operates to cut off the flow of air to said fluid-actuated piston, and mechanical means driven by a moving part of the engine for periodically moving said cut-off valve off of its seat to admit compressed air against said 85 fluid-actuated piston. 90
- 95 102. In an internal combustion engine, in combination, power cylinders and scavenging cylinders and pistons in tandem, an air manifold, said engine having passages for admitting compressed air to said scavenging cylinders and for admitting air from said scavenging cylinders to said manifold for scavenging said power cylinders, a rotary valve controlling said passages, a fluid actuated piston connected with said rotary valve to actuate the same, a cut-off valve, a valve seat co-operating therewith to cut off from or admit air against said fluid-actuated piston, means for admitting air against said valve 100 to move the same against said seat, and a cam for actuating said cut-off valve when the same is on its seat to open the said cut-off valve and permit the same to close. 105
- 110 103. In an internal combustion engine, in combination, power cylinders and scavenging cylinders and pistons in tandem, an air manifold, said engine having passages for admitting compressed air to said scavenging cylinders and for admitting air 115 to said scavenging cylinders and for admitting air 120
- 125

- from said scavenging cylinders to said manifold for scavenging said power cylinders, a rotary valve controlling said passages, a fluid actuated piston connected with said rotary valve to actuate the same, 5 a cut-off valve, a valve seat coöperating therewith to cut off or admit air to said fluid-actuated piston, means for admitting air against said valve to move the same 10 against said seat, and a cam for actuating said cut-off valve when the same is on its seat to open the said cut-off valve and permit the same to close, said cut-off valve corresponding to one direction of running of 15 the engine, a second cut-off valve corresponding to the other direction of running of the engine for cutting off and admitting compressed air to said fluid actuated piston, and a seat coöperating with said second named cut-off valve, means for admitting compressed air against said second named cut-off valve to move the same against its seat, and a cam for operating said second cut-off valve when on its seat to open the 20 same to admit air against said fluid actuated piston.
104. The method of starting a Diesel type engine which consists in rotating the engine shaft by means of compressed air admitted 25 to an air cylinder other than the fuel burning cylinder of the engine, exhausting the compressed air from said cylinder after it has performed its work of rotating the shaft until its pressure is approximately atmospheric pressure, and then utilizing the remaining air to scavenge the fuel burning cylinder.
105. The method of starting a multicylinder Diesel type engine which consists in rotating the engine shaft by means of compressed air admitted to starting cylinders other than the fuel burning cylinders of the engine, exhausting the compressed air from 30 said starting cylinders after it has performed its work of rotating the shaft until its pressure is approximately atmospheric pressure, then discharging and confining the remaining air from the different starting cylinders and scavenging the fuel burning cylinders with the air so confined.
106. The method of starting and driving a Diesel type engine which consists in rotating the engine shaft by means of compressed air admitted to an air cylinder other than 35 the fuel burning cylinder of the engine, exhausting the compressed air from said air cylinder after it has performed its work of rotating the shaft until its pressure is approximately atmospheric pressure, scavenging the fuel burning cylinder with the remaining air, supplying fuel to the fuel burning cylinder of the engine, cutting off the supply of compressed air and scavenging the fuel burning cylinder thereafter with free 40 air admitted to the same air cylinder.

107. The method of starting a Diesel type engine which consists in rotating the engine shaft by means of compressed air, permitting the expansion and escape of a portion of the said compressed air until the pressure of the remaining air is substantially atmospheric pressure, and then utilizing the remaining air to scavenge the fuel burning cylinder.

108. The method of starting a Diesel type engine which consists in rotating the engine shaft by means of compressed air, permitting the expansion and escape of a portion of the said compressed air until the pressure of the remaining air is substantially atmospheric pressure, re-compressing the remaining air to a relatively low pressure by the power exerted by the said compressed air, and then utilizing the said re-compressed air to scavenge the fuel burning cylinder.

109. A control device for an internal combustion engine, comprising, in combination, a hand controlled member, a shaft rotated thereby, a wheel carried by said shaft, starting valves for starting the engine, means for actuating the same by said wheel, and means actuated by said shaft for controlling the fuel admission.

110. A control device for an internal combustion engine, comprising, in combination, 95 a hand wheel, a worm rotated thereby, a worm wheel engaging said worm and actuated thereby, air starting valves actuated by said worm wheel to open, automatic means for closing said valves after said wheel has moved beyond a predetermined point, and means actuated by said worm wheel for controlling the admission of fuel to the engine.

111. A control device for an internal combustion engine, comprising, in combination, 105 a hand wheel, a worm actuated thereby, a worm wheel meshing with said worm and driven thereby, an actuator, means for moving said actuator by said wheel, air starting valves connected with said actuator so as to 110 be opened thereby when moved by said worm wheel, automatic means for releasing said valves and for closing the same after said worm wheel has reached a predetermined point, and means also actuated by the rotation of said hand wheel for controlling the admission of fuel to the engine.

112. A control device for an internal combustion engine, comprising, in combination, a hand wheel, a worm rotatable thereby, a 120 worm wheel meshing with said worm, an actuator in the form of a slide having a pin and slot connection with said worm wheel, means for guiding said actuator when moved by said worm wheel, starting valves arranged to be opened by said actuator, automatic means for releasing said starting valves from the control of said actuator and for closing the same after said actuator has arrived at a predetermined point, and means 125 130

- actuated by said worm wheel for admitting fuel to the engine.
113. A control device for an internal combustion engine, comprising, in combination, 5 a hand wheel, an actuator moved thereby, a lever arranged to be moved by said actuator, a starting valve actuated by the movement of said lever, means for automatically releasing the said lever from said actuator, and fuel controlling means controlled through said hand wheel.
114. A control device for an internal combustion engine, comprising, in combination, 10 a hand wheel, an actuator moved thereby, a lever arranged to be moved by said actuator, a starting valve actuated by the movement of said lever, and fuel controlling means controlled through said hand wheel, said lever having means for holding the same disengaged from said actuator to enable the 15 starting valve to be operated independently.
115. A control device for an internal combustion engine, comprising, in combination, 20 a hand wheel, a worm rotated thereby, a worm wheel meshing with said worm, an actuator mounted to slide adjacent said wheel, a pin and slot connection between said actuator and said worm wheel and arranged to give said slide a progressively decreasing movement for a given rotation of 25 said hand wheel, a starting valve for driving the engine in one direction, another starting valve for driving the engine in the other direction, means for controlling said valves 30 to open either of them by the movement of said actuator, automatic means for releasing the opened valve from the actuator after a predetermined movement of said actuator, means associated with said actuator for preventing the opening of the other valve thereafter, and means actuated by said hand 35 wheel for admitting fuel to the engine.
116. In a reversible internal combustion engine, controlling mechanism comprising, 40 in combination, an actuator, means for moving the same, a lever arranged to be swung in either direction by said actuator, a starting valve for starting the engine in one direction connected with said lever so as to 45 open when said lever is swung in one direction, another starting valve for driving the engine in the other direction connected with said lever so as to open when the lever is 50 swung in the other direction, automatic means for disconnecting the lever from the actuator after a predetermined movement of the actuator to open one of the valves, and means for obstructing the lever after it is 55 released from said actuator to prevent the same being swung to open the other valve. 60
117. In a reversible internal combustion engine, controlling mechanism comprising, 65 in combination, an actuator, a lever arranged to be swung in either direction by said actuator, a starting valve for starting the engine in one direction connected with said lever so as to open when said lever is swung in one direction, another starting valve for driving the engine in the other direction connected with said lever so as to open when 70 the lever is swung in the other direction, automatic means for disconnecting the lever from the actuator after a predetermined movement of the actuator to open one of the valves, means for obstructing the lever 75 after it is released from said actuator to prevent the same being swung to open the other valve, and means for simultaneously moving said actuator and controlling the admission of fuel to the engine. 80
118. In a reversible internal combustion engine, controlling mechanism comprising, 85 in combination, an actuator, a starting valve for starting the engine in one direction controlled by said actuator when it moves in one direction; a second starting valve for starting the engine in the other direction and actuated by a movement of said actuator in the other direction, and means for simultaneously moving said actuator and controlling the admission of fuel to the engine. 90
119. In a reversible internal combustion engine, controlling mechanism comprising, 95 in combination, a rotatable member, an actuator, means on said rotatable member for driving said actuator in one direction when said rotatable member rotates in one direction and for driving the actuator in the other direction when said rotatable member rotates in the other direction, a starting 100 valve for starting the engine actuated by a movement of said actuator in one direction, another starting valve for starting the engine in the other direction and actuated by the movement of said actuator in the other 105 direction, fuel admission means, and means for simultaneously controlling said fuel admission means and said actuator.

In testimony whereof I have hereunto set my hand in presence of two subscribing 110 witnesses.

LEONARD B. HARRIS.
